UNITED STATES PATENT OFFICE.

HERBERT O. TIBBITS, OF CLEVELAND, OHIO.

STAMP-VENDING MACHINE.

1,251,447.

Specification of Letters Patent. Patented Dec. 25, 1917.

Application filed September 13, 1916. Serial No. 119,915.

To all whom it may concern:

Be it known that I, HERBERT O. TIBBITS, a citizen of the United States, residing at Cleveland, in the county of Cuyahoga and State of Ohio, have invented new and useful Improvements in Stamp-Vending Machines, of which the following is a specification.

The invention relates to a vending machine, and more particularly to the class of combination stamp vending and coin changing machines.

The primary object of the invention is the provision of a machine of this character wherein stamps of different denominations will be successively ejected from the machine on the deposit of the proper coins therein and either a single stamp or a predetermined number will be delivered to the operator of the machine when depositing the required amount of money therein.

Another object of the invention is the provision of a machine of this character wherein, on the deposit of one or more coins of different denominations within the machine, the requisite change in lieu thereof will be had having an equal valuation to the amount of the coin or coins deposited so that the change can be redeposited within the machine for the ejecting of the postage stamps therefrom, either singly or any number, according to the money deposited within the machine.

A further object of the invention is the provision of a machine of this character wherein the stamp delivering or ejecting mechanism is of novel form so that the same will be automatically set and operated on the deposit of a coin of a predetermined value for the delivery of a stamp or stamps having the same valuation as the coin deposited within the machine.

A still further object of the invention is the provision of a machine of this character wherein the coin changing mechanism is automatically controlled and operated for delivering the exact aggregate amount of coins of lesser denomination than the amount deposited within the machine, thereby enabling the operator to obtain the required change for deposit in the machine in procuring stamps therefrom in exchange for the deposit.

A still further object of the invention is

the provision of a machine of this character wherein the stamp or stamps ejected from the machine are severed automatically from the strip or strips of stamps, which are in tape form within the machine, when the said stamp or stamps are delivered therefrom, thus making it impossible for any one to surreptitiously obtain more stamps than entitled to in accordance with the deposit made within the machine.

A still further object of the invention is the provision of a machine of this character wherein the stamp ejecting or delivering mechanism is positive in action and is automatically controlled to avoid any possibility of theft of the stamps by a surreptitious attempt on the part of the operator of the machine to extract stamps in excess of the number delivered in accordance with the value or valuation of the coin deposited therein while the machine is being operated.

A still further object of the invention is the provision of a machine of this character wherein the coin changing mechanism is automatically controlled so as to avoid tampering therewith or the possibility of obtaining change having valuation greater than the amount of the coin valuation deposited within the machine.

A still further object of the invention is the provision of a machine of this character wherein the coin ejecting or delivering mechanism and the coin changing mechanism are of novel form so as to assure positiveness in their operation and to effect the proper and successful delivery of both stamps and coins from the machine.

A still further object of the invention is the provision of a machine of this character wherein the number of stamps delivered from the machine is automatically counted so that at a glance it can be determined the exact number of stamps ejected therefrom.

A still further object of the invention is the provision of a machine of this character wherein, on the delivery of all of the stamps therefrom and also the delivery of the coins from the change mechanism, the said machine will be rendered inoperative and this fact will be indicated so that any attempt to operate the machine when in this condition will be prevented.

A still further object of the invention is

the provision of a machine of this character wherein, on the deposit of a spurious coin therein, or a coin of improper valuation, it will be returned to the depositor without enabling the operation of the machine for the obtaining of stamps or change therefrom by such depositor.

A still further object of the invention is the provision of a machine of this character wherein, on the deposit of small denominations of coins for the procuring of stamps therefrom, the said coins will be supplied or introduced into the coin changing mechanism until the latter is filled to its capacity and thereafter the excess coins are automatically delivered to a depository within the machine, and in this manner the coin changing mechanism will be constantly supplied with the requisite coins for the changing of larger denominations of coin deposited within the machine when change is required by the depositor.

A still further object of the invention is the provision of a machine of this character which is simple in construction, thoroughly reliable and efficient in its operation, strong, durable, automatic in action and inexpensive in manufacture.

Other objects will be in part obvious and in part hereinafter set forth.

The invention accordingly consists in the features of construction, combination of elements and arrangement of parts which will be exemplified in the construction hereinafter described, and the scope of the application of which is indicated in the appended claims.

In the accompanying drawings:

Figure 1 is a perspective view of the machine constructed in accordance with the invention;

Fig. 2 is a front elevation thereof, with the front wall and top removed;

Fig. 3 is a sectional view on the line 3—3 of Fig. 2;

Fig. 4 is a sectional view on the line 4—4 of Fig. 2;

Fig. 5 is a front elevation of the movable coin carrier and chutes, with the shank portions thereof broken away;

Fig. 6 is a vertical longitudinal sectional view of the carrier and chutes;

Fig. 7 is a sectional view on the line 7—7 of Fig. 5, looking in the direction of the arrows;

Fig. 8 is a sectional view on the line 8—8 of Fig. 5, looking in the direction of the arrows;

Fig. 9 is a sectional view on the line 9—9 of Fig. 6, looking in the direction of the arrows;

Fig. 10 is a sectional view on the line 10—10 of Fig. 5;

Fig. 11 is a view similar to Fig. 10, showing in detail the position of a different

denomination of coin therein than that shown in Fig. 10;

Fig. 12 is a fragmentary vertical transverse sectional view showing by full lines the adjusted position of the carrier and the relative position of the coin stops carried thereby, while by dotted lines is shown an adjusted position thereof;

Fig. 13 is a fragmentary vertical sectional view showing in detail by full lines and dotted lines adjusted positions of the carrier with the lock dog therefor;

Fig. 14 is a sectional view on the line 14—14 of Fig. 3;

Figs. 15, 16 and 17 are fragmentary plan views similar to Fig. 14, showing the parts in different positions;

Fig. 18 is a fragmentary perspective view showing certain of the parts of Fig. 14 separated from each other;

Fig. 19 is a sectional view on the line 19—19 of Fig. 14;

Figs. 20, 21, 22, 23, 24 and 25 are detail views showing various positions of the ratchet and lock mechanism of the stamp ejecting mechanism;

Fig. 26 is a perspective view of one of the lock dogs;

Fig. 27 is a perspective view of one of the ratchet dogs;

Fig. 28 is a fragmentary vertical transverse sectional view showing the lock control of the stamp ejecting mechanism and the means for effecting the ejecting of the deposited coin within the machine;

Fig. 29 is a fragmentary vertical sectional view showing the position of certain parts of the feed mechanism of the stamp ejecting mechanism;

Fig. 30 is a fragmentary horizontal sectional view showing parts of the feed mechanism in top plan;

Fig. 31 is a detail side elevation of the lock for the feed mechanism;

Fig. 32 is a detail view similar to Fig. 29, showing the parts of the feed mechanism in adjusted position when acted upon by a coin;

Fig. 33 is a view similar to Fig. 31, showing the release of the lock for the feed mechanism;

Fig. 34 is a detail side view showing the release of the lock for the stamp ejecting mechanism;

Fig. 35 is a view similar to Fig. 32, showing the feed mechanism advanced;

Fig. 36 is a view similar to Fig. 31, showing a different position of the feed wheel for a further step in the movement of the lock therefor;

Fig. 37 is a fragmentary perspective view, partly in section, showing part of the feed and lock mechanism with the parts separated;

Fig. 38 is a fragmentary side elevation

showing the relative positions of the trips for one of the coin stops on the coin carrier and chute;

Fig. 39 is a sectional view on the line 5 39-39 of Fig. 38;

Fig. 40 is a detail perspective view of one of the levers for actuating the trip for the coin stop shown in Fig. 38;

Fig. 41 is a sectional view on the line 10 41-41 of Fig. 4;

Fig. 42 is a fragmentary vertical transverse sectional view showing in detail certain parts of the coin changing mechanism in adjusted position;

Fig. 43 is a sectional view on the line 15 43-43 of Fig. 47, looking in the direction of the arrows;

Fig. 44 is a detail side elevation of certain parts of the coin changing mechanism 20 for the automatic adjustment thereof;

Fig. 45 is a view similar to Fig. 42, with the parts in different positions;

Fig. 46 is a detail vertical sectional view showing the operating part for the stop in 25 position to permit the operation of the coin changing mechanism;

Fig. 47 is a fragmentary vertical sectional view showing the parts in Fig. 46 in position for rendering the coin changing mechanism ineffective;

Fig. 47^a is a sectional detail on the line 47^a-47^a of Fig. 47;

Fig. 48 is a sectional perspective view showing the relative position of the parts 25 in Fig. 46;

Fig. 49 is a perspective view showing in detail certain parts of the coin changing mechanism;

Fig. 50 is a perspective view of the ejector 20 slide of the coin changing mechanism;

Fig. 51 is a perspective view of the balancing lever of the change controlling mechanism;

Fig. 52 is a fragmentary vertical sectional 45 view showing in detail the indicator mechanism;

Fig. 53 is a fragmentary front elevation thereof;

Fig. 54 is a fragmentary perspective view 50 of one of the indicators;

Fig. 55 is a fragmentary horizontal sectional view through the stamp roll spool, showing the manner of mounting thereof;

Fig. 56 is a fragmentary sectional elevation 55 showing another indicator for the change mechanism;

Fig. 57 is a fragmentary perspective view of the indicator;

Fig. 58 is a fragmentary transverse sectional view showing in detail the stamp severing mechanism;

Fig. 59 is a view similar to Fig. 58, showing the parts in adjusted position;

Fig. 60 is a sectional view on the line 65 60-60 of Fig. 58;

Fig. 61 is a fragmentary perspective view showing the trip for the cutting or severing mechanism;

Fig. 62 is a perspective view of the releasing and resetting levers of said cutting 70 or severing mechanism;

Fig. 63 is a perspective view of the hanger for the cutting blades;

Fig. 64 is a sectional view on the line 75 64-64 of Fig. 60;

Fig. 65 is a view similar to Fig. 29, showing a slight modification of the feed mechanism;

Fig. 66 is a detail side elevation of the feed wheel;

Fig. 67 is a fragmentary detail sectional view through one of the coin slots showing a coin detector supported relative thereto;

Fig. 68 is a fragmentary elevation showing in detail the support and one of the 85 magnets constituting the coin detector.

Referring to the drawings in detail, A designates generally the casing of the vending machine, which includes a frame 10 and panels 11 preferably made from metal, the 90 panels constituting the walls of the casing and being securely fastened in the frame 10, and this casing is of the required shape and design, having a curvilinear top 12 supporting a cross bar or plate 13 provided with 95 a series of slots 14 adapted to receive coins of different denominations for the introduction thereof into the machine, while in the front of the said casing A are the stamp delivering slots or openings 15 and coin discharge openings 16 respectively. Arranged about the stamp delivery slots 15 are escutcheon plates 17 and also about the change discharge opening 16 is an escutcheon plate 18 which carries a cup-like receiver 19 for 100 the coins delivered through the opening.

Arranged rearwardly of the bar or plate 13 and rising vertically from the top 12 of the casing A is a label holder 20 in which are arranged a series of labels 21, having 110 printed or otherwise marked thereon indicia indicative of the denomination of coin to be inserted in the machine for the delivery of stamps therefrom and also the delivery of change in accordance with the deposit within 115 the machine.

Formed in the casing A and the escutcheon plate 17 below the stamp delivery openings 15 are peep slots 22 for permitting the inspection of counter mechanism to enable a 120 person to determine the exact number of stamps ejected from the machine, the counter mechanism being hereinafter fully described.

Arranged within the casing A is the stamp 125 ejecting or delivering mechanism which comprises superposed spaced horizontally arranged shafts 23 and 24 respectively, both of which are supported in brackets 25 fixed to the front corner posts of the frame 10 in the upper portion thereof, the brackets 25 130

being formed with substantially inverted L-shaped slots 26 for slidably receiving the shaft 23 so that it can be moved away from or toward the shaft 24, the latter being journaled in the brackets 25 in fixed relation to the same.

Loosely journaled on the shaft 24 is a pair of stamp feeding rollers 27, while loosely journaled upon the shaft 23 are presser or 10 guide rollers 28 which coöperate with the feed rollers 27 for the ejecting of stamps through the openings 15 in the front wall of the casing A from between the said rollers in a manner presently described.

15 Each feed roller 27 is formed with an- nular edge flanges 29 which serve as guides between which works the guide roller 28 so that both the feed and said guide rollers will be held against relative movement longitudinally of the shafts 23 and 24 supporting the same, and in this manner the said rollers are held in alinement with each other. Each 20 of the rollers 27 and 28 is formed with a hub extension 30 and these extensions have 25 fixed thereto gears 31 meshing with each other so that the rollers will rotate in unison in reverse directions to each other for the positive feeding of the stamps, the peripheral surfaces of the rollers being suitably 30 roughened at 32 to avoid the slipping thereof when contacting with the said stamps. Arranged below the shaft 24 and fixed to the front corner posts of the frame 10 is a horizontal bar 33 to which are fixed coiled re- 35 tractile springs 34, the same being also fixed to the shaft 23 and serve to tension the rollers 28 to hold the same in close relation to the rollers 27 for the positive gripping of the stamps therebetween to assure the 40 feeding of the stamps during the ejecting or delivery operation of the machine.

Below the feed rollers 27 and secured to the horizontal bar 33 are suitable resetting counting devices 35 which are visible 45 through the peep slots 22 in the front wall of the casing A and are connected through the medium of gears 36 with the gears 31 so that on the rotation of the feed rollers 27 the counting devices 35 will be simultane- 50 ously operated for the counting of the stamps ejected or delivered from the machine, thus enabling a person to determine the exact number of stamps delivered.

Rearwardly of the feed rollers 27 and 55 supported upon horizontal side bars 37 mounted in the frame 10 is a platform 38, from which rise spaced pairs of guide ears 39 in which are mounted rocking latch pawls 40 and sliding feed dogs 41 respectively, 60 both of which are acted upon through the medium of springs 42 which normally hold the same in working position, while formed on each of the feed rollers 27 are the notched latch wheels 43 and the ratchet feed wheels

44 respectively, which are adapted to be 65 acted upon by the latch pawls 40 and the feed dog 41, the springs 42 being designed to normally hold the latch pawls 40 in positive engagement with the latch wheels 43, thereby locking the feed rollers 27 against 70 rotation while the feed dogs 41 are normally out of engagement with the feed rollers 44 for operation in a manner presently described. Each ratchet feed wheel 44 has its teeth formed with hook-like shoulders 45 75 and likewise the engaging ends of the feed dogs 41 are formed with hook-like shoulders 46 to coöperate with the shoulders 45, so that when the feed dogs 41 have been ini- 80 tially advanced for moving the feed wheels 44 a single tooth it will be impossible for any one to pull upon the stamp strip to cause outward feeding thereof and thereby fraudu- 85 lently obtain an excessive number of stamps over the amount or valuation of the coin 85 deposited for the operation of the stamp ejecting or delivering mechanism. In other words, the feed rollers 27 are blocked against rotation for the ejecting of the strips of 90 stamps after the feed dogs 41 have been started in their advance movement or at any time from the initial advancement thereof until the completed advance movement of the same whence the latch pawls 40 have be- 95 come engaged with the latch wheels 43 and in this manner the possibility of fraudulent manipulation of the stamp ejecting or de- 100 livering mechanism is eliminated.

Mounted in the latch pawls 40 are trip pins 47 which project into the path of move- 100 ment of cams 48 formed on the feed dogs 41 so that on the advancement of the latter the said cams 48 will act upon the pins 47 to effect the lifting of the latch pawls 40 out of engagement with the latch wheels 43, thereby unlatching the feed rollers 27 to be rotated by the feed dogs 41 engaging the ratchet feed wheels 44 forming a part of the 105 said rollers so that stamps will be ejected or delivered from the machine.

Mounted upon the back corner post of the frame A are bearings 49 in which are journaled trunnions 50 of a coin carrier comprising a downwardly tapered housing 51 having formed interiorly thereof the coin chutes 115 or slots 52, 53, 54 and 55, respectively, the upper ends of which are adapted to register with the slots 14 in the bar or plate 13 on the top 12 of the casing A for the deposit or introduction of coins therein, the chute 54 120 being adapted to receive coins of the valuation of one cent or penny, the chute 55 adapted to receive the coins of twenty-five and fifty cent valuation, the chute 53 adapt- 125 ed to receive coins of five cent valuation and the chute 52 to receive coins of ten cent valuation, and these coins are adapted to be carried in the housing 51 of the carrier for op-

erating the stamp ejecting or delivery mechanism and the coin changing mechanism in a manner presently described.

The chute 54 is formed with lateral passages 55' and 56, respectively, at its lowermost end for the positioning of one or two one cent or penny coins in said passages 55' and 56 to close holes 57 and 58, respectively, formed in the housing 51 for intersecting the said passages 55', and 56 for the operation of an actuating fork 59 slidably mounted upon the platform 38, the said fork being supported for swinging movement upon a pivot 60 which is fixed in a runner 61 movable on the platform 38 which is formed with a guide slot 62 receiving a guide plate 63 secured to the runner 61, and to this plate is connected a follower 64 which holds it in the slot 62, and in this manner the fork 59 is guided in its movement on the platform 38, the pivot 60 being surrounded by a coiled tension spring 65 which acts upon the fork 59 to hold the same in its shifted position when swung either to the right or to the left of the machine. The fork 59 has formed in one limb a notch 66 to receive a pin 68 fixed in one of the feed dogs 41, while the other limb of the fork 59 is adapted to engage a pin 67 mounted in the other feed dog 41, and this fork 59 alternately engages the respective pins 67 and 68 carried by the feed dogs for the operation of the same to effect the independent rotation of the feed rollers 27 to eject or deliver from the machine stamps of different denominations. The fork 59 at its rearmost end is formed with abutment wings 69 which are engaged by the housing 51 of the carrier so that the said fork 59 will be automatically moved to a neutral point for its ineffectiveness on the feed dogs 41 when the carrier is advanced or swung forwardly without coins of the one cent or penny valuation being deposited therein to close the holes 57 and 58 thus preventing the operation of the stamp ejecting or delivering mechanism. Cut from the platform 38 and struck upwardly therefrom are bearings 70 to which is pivoted a yoke 71 having mounted therein an operating handle 72 which protrudes without the casing A at the top 12 thereof through a slot 73 formed in said top 12, and this handle 72 is adapted to work in the slot 73 for the movement of the yoke 71 by hand. Pivoted to the yoke 71 so that on the swinging of the yoke 71 forwardly the carrier is likewise moved in this direction, is a U-shaped bail 74 which is also pivoted to the housing 51 of the carrier so that on the swinging of the yoke 71 forwardly the carrier is likewise moved in this direction, and to this bail 74 at the rear of the housing 51 is connected a coiled retractile spring 75 which is also connected to the frame 10 of the casing A, the spring 75 being

designed to return the carrier to normal position or move the same rearwardly after its forward movement by operating the handle 72 by hand.

Formed in the front wall of the housing 51 of the carrier below the holes 57 and 58 is a slot 76, while formed on the said front wall of the housing 51 at a point above the holes 57 and 58 is a hanger 77 in which is pivoted a weighted trip yoke 78 carrying a coin stop 79 normally projected through the slot 76 into the path of movement of the coins within the passages 55' and 56 of the chute 54 so as to hold the coins deposited therein for closing the holes 57 and 58 and positioning the said coins in the path of fingers 80 and 81, respectively, the finger 80 being longer than the finger 81 so that when engaged by a coin closing the hole 57 the fork 59 will be automatically thrown to the right hand side of the machine for the engagement of its other limb with the pin 68 so that in this manner the feed rollers 27 are independently operated. The chute 54 is formed with a deflector wall 82 which serves to deflect a single coin of the proper denomination, namely, one cent or penny, into the right hand passage 56 so that this coin will engage the finger 81 for the automatic shifting of the fork 59 to bring the same into a position for engaging the pin 68 carried by the dog 41 at the left hand side of the machine and thus the feed roller 27 at this side will be operated on the swinging of the carrier in a forward direction to eject a stamp having a like valuation of the coin deposited within the carrier. It will be impossible to operate the feed roller 27 at the right hand side of the machine when a single coin has been inserted in the chute 54. However, on the insertion of a second coin of the one cent or penny denomination within the chute 54 the same will enter the passage 55', thus both holes 57 and 58 will be closed in the housing 51, and these coins will be held in position by the stop 79 for this purpose so as to act upon the fork 59 for moving the same to the right when the carrier is swung forwardly, so that the roller 27 at the right hand side of the machine will be operated for the ejecting or delivering of a stamp having a valuation in accordance with the aggregate amount of the two coins of the one cent denomination deposited within the chute 54 in the carrier.

Mounted at the back of the frame 10 and adapted to project through an opening 83 formed in the housing 51 is a trip spring 84, the tip 85 of which is adapted for engagement with the stop 79 on the rearward movement of the carrier for disengaging the stop from the slot 76 in said housing to permit the coins within the passages 55' and 56 to pass out of the same into the opening 83 for

the discharge of the said coins into a trough 86 stationarily mounted on the frame and projected through the opening 83 in said housing for the discharge of the coins from 5 the chute 54 into the coin changing mechanism hereinafter fully described.

The spring 84 rearwardly of the tip 85 is formed with a swell 87 which engages one edge of the opening 83 so as to automatically 10 disengage the tip 85 from the stop 79 on the rearward movement of the carrier for permitting the stop 79 to assume normal position within the slot 76 in the housing 51 and thereby retain coins of the proper denomination 15 deposited within the chute 54 in the carrier for the further operation of the machine. The passages 55' and 56 are formed with nibs 88 so as to properly contract the said passages to assure the retention of the 20 proper coins deposited within the chute 54, yet if an improper coin, that is, one of a smaller size than the coin having the valuation of one cent or penny, is deposited therein the same will pass the nibs 88 and be 25 delivered from the machine for its return to the depositor in a manner presently described.

Secured centrally to the horizontal bar 33 below the shaft 24 centrally thereof is an inverted substantially L-shaped bracket 89, on the horizontal portion of which is fixed a bearing 90 having secured therein a shaft 91 on which are journaled feed gears 92 which are arranged at opposite sides of the bracket 35 89 and each is formed with a hub 93, in the inner end of which are mounted at intervals feed lugs 94 which, in this instance, are four in number, and are concentrically disposed about the hub, while formed in the inner side 40 of each gear 92 is an annular groove 95 providing an internal annular shoulder 96 having at intervals therein notches 97 which are disposed an equal distance apart and likewise the feed lugs 94 are disposed an equal distance 45 apart. Secured to the bearing 90 is a hanger 98 to which is fixed the forward end of a rectangular shaped forwardly inclined guide frame 99, the rear end of which is fixed to the bracket 89, and in this frame 50 are mounted sliding plungers 100 having pivotally mounted in each a feed dog 101 which is formed with a notch 102 in its free end to receive any one of the lugs 94, and this dog is acted upon by means of a spring 103 55 carried by the plunger 100 so as to hold it in the path of the lugs 94 for positive engagement therewith. Arranged within the grooves 95 in the gears 92 are latch pawls 104, which are formed with a tooth 105 for 60 engagement in any one of the notches 97 in the shoulders 96, and these latch pawls 104 are supported upon a spring 106 fixed upon a bracket 107 mounted on the frame 99, which spring serves to hold the pawls normally in latched engagement with the gears 65

92, the pawls 104 being formed with elongated slots 109 through which work pins 108 suitably mounted in the sides of the frame 99 and also said pins 108 engage in openings 111 in hanger blocks 112 loosely 70 mounted in the grooves 95 in the gears 92, the latching pawls 104 being formed with trip extensions 113 provided with cams 114 which engage and are acted upon by the pivots 115 connecting the feed dogs 101 to 75 the plungers 100, which pivots 115 extend through elongated slots 116 formed in the side of the frame 99 to protrude into the path of the cams 114 so that on the advancement of the plungers 100 the pivots 115 will 80 engage the cams 114 to move the extensions 113 and likewise move the latch pawls 104 out of engagement with the gears 92 and at the same time the feed dogs 101 will engage the lugs 94 for rotating the said gears 92 85 which mesh with pinions 117 loosely journaled upon the shaft 24, the pinions being formed with clutch members 118 which are adapted for locking engagement with companion clutch members 119 formed on the 90 feed rollers 27, the pinions 117 being acted upon by means of coiled expansion springs 120 which surround the shaft 24 so that the clutch members 118 will lock with the companion clutch members 119 when the gears 92 95 are rotated for the turning of the feed rollers 27 to eject or deliver stamps in predetermined numbers from the machine.

Connected with the guide frame 99 are leaf springs 121 which are also connected 100 with the plungers 100 so as to hold the same in normal position to be acted upon by coins deposited within the carrier when the latter is advanced.

Formed in the housing 51 of the carrier 105 below the opening 83 therein are holes 122 which intersect the chute 55 and are adapted to be closed by coins deposited within said chute, the coins being stopped during the gravitation thereof within the chute 55 to 110 position the same for closing the holes 122 by means of trip stops 123 which are supported upon weighted yokes 124 pivotally mounted upon the housing 51 and working within a suitable slot formed in the latter, 115 and these coins, when closing the holes 122, will engage the plungers 100 when the carrier is moved forwardly so that the plungers will be actuated for the unlatching and turning of the gears 92 which, in their turn, rotate the feed rollers 27 for ejecting a predetermined number of stamps for the delivering 120 of the same from the machine.

Detachably mounted upon the ends of the shaft 91 are stamp reels 125 on which are 125 normally wound stamp strips 126, which latter are trained over guide rolls 127 and between the rollers 27 and 28, the said reels 125 being detachably fastened upon the ends of the shaft 91 through the medium of cot- 130

ter pins 128 against which work tension springs 129 surrounding the ends of the shaft 91 and acting against the reels 125 to hold the same in proper alinement relative 5 to the guide rolls 127 for the proper feeding of the strips 126 from the reels during the operation of the feeding mechanism of the machine. Mounted in the slot 62 in the platform 38 is a leaf spring 130 which 10 acts upon the runner 61 to hold the fork 59 normally in rearmost position.

Pivoted to the frame rearwardly of the carrier are L-shaped rocking arms 131 which have connected thereto leaf springs 132, the same acting against the frame so as to hold the arms 131 in normally forwardly tilted position, and upon these arms forwardly of the carrier are formed up-standing posts 133 in which are pivoted 20 weighted trip dogs 134 which are adapted to act upon the stops 123 on the rearward movement of the carrier for the tripping of the said stops, whereby the coins within the chute 55 will be freed therein for the deposit 25 of the same within the machine and also to allow the dropping of the coin out of the path of the plungers 100 so that they will become inactive when the holes 122 in the housing 51 are opened by the deposit 30 of the coins within the machine. These dogs 134 are in the form of gravity dogs and are limited in their movement in one direction by the posts 133 so that on the forward movement of the carrier the stops 123 will 35 ride over the dogs should the same be in the path thereof, and on the reverse or rearward movement of the carrier the dogs 134 will engage the stops 123 to momentarily trip the same for the release of the coins 40 within the chute 55 of the carrier, the raising and lowering of the arms 131 being effected in a manner presently described. The bracket 89 in its vertical portion is slotted or bifurcated at 135 to receive the 45 forward end of the arms 131 and to permit play thereof and to hangers 143 at opposite sides of the bifurcation 135 are secured lateral extensions 136 to which are pivoted lifting levers or arms 137 which are formed 50 in their free ends with notches 138 receiving the forward ends of the arms 131, and engaged in these levers or arms 137 are hooked ends 139 of lifting members 140 which are pivoted for swinging movement 55 in a bracket 141 supported in the frame 10, while mounted in the outer sides of the gears 92 are lifting pins 142 which engage with the members 140 for lifting the same on a complete revolution of each of the gears 60 92 so that the arms 131 will be automatically lifted for bringing the dogs 134 into position for the tripping of the stops 123 to free the coins within the chute 55 at determined intervals. It will of course be 65 noted that each arm 131 is automatically

lifted independently of the other arm so that the coins of different denominations will be freed independently of each other when deposited within the chute 55, one coin, when so deposited, being adapted to operate the feed mechanism for the delivery of a predetermined number of stamps of a certain valuation while the other coin, when deposited, is adapted to operate the feed mechanism for the delivery or ejecting of a predetermined number of stamps of another valuation. When the pins 142 ride out of engagement with the lifting members 140 the springs 132 on the arms 131 become active for automatically lowering the said arms 80 so that the trip dogs 134 will be out of the path of the stops 123 and thus prevent the tripping thereof during the movement of the carrier for the further various operations of the machine, as will be hereinafter 85 fully described.

Secured to the platform 38 and to the horizontal bar 33 on the frame are vertically disposed hangers 143 in which are slidably mounted trip rods 144, the same 90 being also slideable through the platform 38 and are formed at their upper ends with hooks 145 which act upon the latch pawls 40 so as to release the same from the latch wheels 43 on the downward movement of 95 the said trip rods 144, while the opposite ends of the said trip rods 144 are forwardly and upwardly curved or bent at 146, with the extremities thereof pivoted at 147 to the latch pawls 104 so that on the disengagement of the teeth 105 thereon from the notches 97 for the freeing of the gears 92 the trip rods 144 will become active for the engagement of the hooks 145 thereon with the latch pawls 40 for disengaging the same 100 from the latch wheels 43 of the feed rollers 27 so that when the gears 92 are rotated the said feed rollers 27 are actuated for ejecting or delivering a predetermined number 105 of stamps from the machine. Of course it is understood that only one of the gears 92 is operated at a time or, in other words, the said gears 92 alternately operate according to the deposit of coin within the machine.

The pins 47 on the latch pawls 40 engage 110 with the rearmost ears 39 on the platform 38 to limit the rearward movement of the said pawls, while the pins 67 and 68 on the feed dogs 41 are designed to engage the foremost ears 39 on the platform 38 to limit 115 the rearward movement of the said feed dogs after being advanced by the coins deposited within the housing 51 of the carrier.

The coin changing mechanism comprises 120 a vertically disposed tubular column or cylinder 148 which, at its lower end, is fixed to and rises from a bridge 149 secured to the front and back of the frame 10 substantially centrally thereof, the column or cylinder 148 being forward of the bridge 149 and formed 125 130

with a bifurcated upper end 150 forming openings 151 and 152 at the front and back respectively thereof. Leading to the opening 151 is a feed spout 153 which communicates with the trough 86 so that the coins introduced into the chute 54 in the housing 51 of the carrier will be dropped into the trough 86 when said coins are free in the housing, and these coins will gravitate from 5 the said trough into the feed spout 153 and thence through the opening 151 into the column or cylinder 148 until the latter has become filled to its fullest capacity, whence the excess coins will ride over the stacked 10 coins in the column or cylinder 148 through the opening 152 into a chute 154 which delivers the excess coins into one of the pockets 155 formed in a coin tray 156 which is removably placed within the casing A and 15 rests upon the bottom thereof for receiving different denominations of coins deposited 20 within the machine.

Fixed to the bridge 149 and rising vertically therefrom rearwardly of the coin column or cylinder 148 is a guide frame 157 in which are mounted horizontally disposed slideable plungers 158 and 159 respectively, while mounted on the inverted L-shaped bracket 89 immediately below the spout 153 25 is a bearing 160 in which is pivoted a swinging lever 161, the same working through the respective slots 162 and 163 formed in the guide frame 157 and has its lower end engaged in a notch 164 formed in an adjustable ejector slide 165 mounted for movement in a guideway 166 formed in the bridge 149 and also for movement in the slot 163 in the frame 157, which slot alines with said guideway 166 so as to pass through a bifurcation 30 167 formed in the lower end of the column or cylinder 148 to eject a predetermined number of coins from the latter through the front discharge opening 168 in the lower end of said column or cylinder for the delivery of the coins into the cup shaped receiver 19 on the front of the casing A of the machine. The slide 165 at the rear end thereof and near the upper edge has fixed therein a fulcrum pin 169 which engages the 35 bridge 149 during the movement of the said slide and thus the latter is free for vertical adjustment on the fulcrum pin 169, while mounted near the front end of the said slide near the lower edge thereof is a bearing pin 170 which rests upon the limbs of a fork 171 formed on and at right angles to a vertically movable gate 172 which is provided with a discharge opening 173 adapted to register with the front opening 168 in the column or 40 cylinder 148, and the position of this gate 172 determines the number of coins to be ejected from the column or cylinder by the ejector slide 165 when actuated in a manner presently described. The gate 172 has 45 formed at its upper end a right angular ex-

tension 174 which is provided with a suitable opening receiving the column or cylinder 148, and in this manner the gate 172 is slidably fitted upon the latter.

The plunger 159 is formed with a cam rib 70 175, while rising from the extension 174 is a slotted eye 176 through which works the plunger 159 so that the cam 175 will act upon the eye 176 when the plunger is advanced for the lifting of the gate 172 to increase the extent of the opening 168 in the column or cylinder 148 and thereby permit a greater number of coins to be discharged or ejected therefrom than when the gate is in its normal lowermost position, the weight 75 80 of the said gate serving to cause the gravitation thereof to its lowermost position when not acted upon by the cam 175, the plungers 158 and 159 being fitted with pins 177 which extend into position for engagement 85 with the lever 161 so that on the advancement of either of the plungers the said lever 161 will be moved for actuating the ejector slide 165 to discharge a predetermined number of coins from the coin column or cylinder 90 148 into the cup shaped receiver 19 at the front of the casing of the machine. Mounted in the slot 162 in the frame 159 is a leaf spring 178 which acts upon the lever 161 so as to return the same to normal 95 rearmost position and also to return the plungers 158 and 159 simultaneously therewith after the said plungers have been advanced.

When the lever 161 moves rearwardly it 100 also draws with it the ejector slide 165 to the rearmost end of the guideway 166 in the bridge 149, as will be apparent, the plungers being acted upon and advanced in a manner presently described. Arranged below the bridge 149 is a weight beam 179, the forward end of which supports vertically disposed rest wings 180 which work through slots 181 formed in the said bridge, and these rest wings are adapted to protrude 110 into the column or cylinder 148 so that the coins deposited within the latter will fall upon the wings 180, and adjustably mounted upon the other end of the beam 179 is a weight 182, which latter serves to normally 115 overbalance the beam 179 so as to hold a predetermined number of coins elevated within the column or cylinder 148 to avoid the discharge of the coins from the said column or cylinder until a predetermined 120 number of coins have been delivered to the column or cylinder to overcome the weight 182, and in this manner the possibility of delivering short change for the value of the coin deposited within the carrier for actuating the coin changing mechanism is eliminated and avoided.

Formed in the housing 51 of the carrier are openings 183 and 184 respectively, both of which are in the path of the plungers 158 130

and 159 and intersect the chutes 52 and 53 within the said housing 51 so that when coins of two determined denominations have been deposited within the chutes 52 and 53 5 the same will gravitate into position for closing the said openings 183 and 184, and these coins are held in this position by means of a coin stop 185 which works through a slot 186 in the front wall of the 10 housing 51 below the openings 183 and 184, and said stop is supported upon a weighted swinging yoke 187 pivoted on the front wall of the housing 51, the weighted yoke being designed to hold the stop normally in the 15 slot 186 to block the coins deposited within the chutes 52 and 53. When the coins close either of the openings 183 and 184 and the housing 51 constituting the carrier is advanced either of the plungers 158 or 159 20 will be moved forwardly for operating the lever 161 which moves the ejector slide 165 and thereby ejects a predetermined number of coins from the column or cylinder 148 according to the valuation of the coin deposited 25 within either chute 152 or 153 in the carrier, thus giving the requisite change to the depositor for the coin deposited so that the smaller denominations of coins delivered from the machine can be used for 30 deposit in the machine to actuate the stamp ejecting or delivering mechanism. Pivoted to the rear end of the weight beam 179 is a vertical arm 188 which is formed at its upper end with a forwardly extending stop 35 189, the latter adapted, when in one position, to engage with a finger 190 formed on and depending from the stop 185 and when the said stop 189 is in another position the finger 190 escapes the said stop 189, but when 40 the finger is engaged with the stop 189 the stop 185 is held out of the slot 186 in the front of the housing so that the coins deposited within the chutes 52 and 53 will pass downwardly and out of the carrier 45 without effecting the operation of the coin changing mechanism, the stop 189 being lifted into the path of movement of the finger 190 when the beam 179 is overbalanced by the weight 182, thus preventing the delivery 50 of coins from the column or cylinder 148 which have an aggregate value less than the value of the denomination of the coin deposited within the carrier so as to avoid the ejecting of a lesser amount of change to the depositor than the value of the said coin deposited and at the same time returning the coin to the depositor in a manner presently described. Fixed to the back of the frame is a trip spring 191 which is adapted to momentarily 55 engage the stop 185 for the tripping thereof on the backward movement of the carrier to permit the freeing of the coins deposited within the chutes 52 and 53 within the housing 51 of said carrier for the deposit 60 of the said coins into the machine. On the advance of the said carrier when the coins are held by the stop 185 to cover the openings 183 and 184, said stop will ride over the trip spring 191 without being tripped so that the coins covering the openings 183 70 and 184 will engage with the plungers 158 and 159 to advance the same for actuating the coin changing mechanism hereinbefore described.

Fixed to the guide frame 157 and also to the back of the frame 10 of the machine below the housing 51 of the carrier is a toothed rack 192, while pivoted to the lower end of said housing 51 is a locking detent or pawl 193 which is adapted to ride on to the rack 80 192 for locking engagement with the teeth thereon during the advance or backward movement of the housing 51 of the carrier so as to prevent reverse movements of the carrier after the same has been initially 85 moved forwardly or rearwardly while the pawl 193 rides upon the rack 192. When the pawl 193 has moved off of the rack 192 the said pawl will gravitate to a position to permit the advance of the carrier or the 90 backward movement thereof, but it is impossible to reverse the movement of the said carrier during either the advancement thereof or the backward movement of the same when the pawl 193 rides on to the rack 192, 95 and in this manner obviates any possibility of repeating operation of either the stamp ejecting or delivering mechanism or the coin changing mechanism.

The stop 189 is formed with a notch 194 100 to permit the said stop to clear the finger 190 after the stop 185 has entered the slot 186 in the front wall of the housing 51 of the carrier so that the weighted beam 179 can rock to overbalancing position either under the influence of the weight 182 or the coins admitted in the column or cylinder 148 so that the change mechanism will be automatically set for the proper delivery of the requisite number of coins in accordance 110 with the valuation of the coin deposited within the machine, thereby obviating any possibility of short change on the deposit of a coin within the machine. Mounted upon the back of the frame immediately below 115 the housing 51 of the carrier is a trough 195 which is formed with the front and back pockets 196 and 197 respectively, and from the back pocket extends a forwardly inclined return chute 198 which has its front 120 end opening into the receiver 19, while extending forwardly from the front pocket 196 is a forwardly inclined chute 199 which has formed in its bottom a slot 200 and also in one side a slot 201, while adjacent to the 125 opening 201 is a deflector wing 202 which is designed to deflect the smaller coin traveling in the chute 199 in the direction of the opening 201 for its discharge therethrough, and on the gravitating of this coin the 130

same engages a deflector plate 203 on the bridge 149 and passes into another pocket 155 in the coin tray 156 for its deposit therein, while the larger coin will ride 5 past the wing 202 and drop through the slot 200 in the chute 199 for its deposit in another pocket 155 in the coin tray 156. The proper coins deposited within the chutes 52 and 53 are stopped at a point for closing 10 the openings 183 and 184 by means of nibs 204, and these coins are not released from the chutes 52 and 53 in the housing 51 of the carrier until the stop 185 has been tripped by the trip spring 191, and when 15 this is effected the housing 51 is at a point over the front pocket 196 so that said coins will be dropped into the latter for their deposit within the machine. Now should there not be a sufficient number of coins in the 20 column or cylinder 148 to be delivered to the depositor aggregating an amount in accordance with the deposit of a predetermined denomination of coin within the machine, the stop 185 is held out of the slot 186 25 in the front of the housing 51 by the stop 189 so that the coin deposited will gravitate from either chute 52 or 53 through the lower end of the housing 51 into the back pocket 197, whence the said coin will roll 30 down the chute 198 and be delivered into the receiver 19, thus it being seen that the coin deposited will be returned to the depositor without possibility of operating the machine, and in this manner obviating delivering 35 short change to the depositor.

In the event that slugs or spurious coins are deposited within the chute 52 in the housing 51 of the carrier the same will gravitate through the said chute and pass 40 the nibs 204, thus rolling into the chute 53, which opens through the lower end of the housing 51 and thus the said slugs or spurious coins will drop into a return chute 205 which is mounted at one side of the trough 45 195 and is forwardly inclined for communication with the cup shaped receiver 19 so that these fraudulent coins will be returned to the depositor.

The chute 54 has its lateral passages 55' 50 and 56 opening into the chutes 53 and 55 respectively, so that spurious coins deposited within the said chute 54 will gravitate past the nibs 88 and fall into either of the chutes 53 or 55, whence the said spurious coins will 55 be discharged through the chute 205 into the receiver 19 and thus be returned to the depositor.

Formed on the front wall of the housing 51 of the carrier is a chute 206 which leads 60 from the slot receiving the stops 123 and opens through the lower end of the said housing 51 so that the coins freed by the stop 123 will be delivered into the chute 206 for the discharge thereof through the lower 65 end of the said chute into a trough 207 at

the other side of the trough 195, and this trough is formed with an opening 208 in one wall thereof, which wall is forwardly inclined so that the smaller coin deposited within the trough will be delivered through 70 the opening 208 and on the dropping of the coin it will engage a deflector wing 209 which directs the smaller coin into another pocket 155 in the tray 156, while the larger coin dropped within the trough 207 will 75 pass the opening 208 and be discharged from the said trough into another pocket 155 of the tray, and in this manner coins of different denominations deposited within the machine will be assorted prior to the deposit 80 thereof within the coin tray on the bottom of the casing interiorly thereof.

In Figs. 58, 59, 60, 61, 62, 63 and 64 there is shown a stamp severing device which comprises a plate 210 suitably mounted forwardly of the feed and guide rollers 27 and 28 and which is formed with slots 211 registering with the stamp openings 15, the lower edges of the slots being outwardly beveled to form shearing edges 212, while pivoted at 213 to the plate are shearing blades 214, the same being also pivoted in a sliding collar 215 mounted for vertical movement upon a guide rod 216 supported in spaced upper and lower ears 217 and 218 respectively. Surrounding the guide rod 216 and working against the upper ear 217 and also working against the sliding collar 215 is a coiled expansion spring 219 which serves to automatically move the shears 214 for their co-operation with the cutting edges 212 so as to sever the stamps from the stamp strip 126, which severed stamps are caught within a receiver 220 mounted on the front wall of the casing A below the stamp opening therein. Mounted on the platform 38 is a bearing 221 to which is pivoted a resetting lever 222 which is engaged by a trip extension 223 on the bail 71 when the latter moves backwardly and the collar 215 has been lowered upon the rod 216 under the action of the spring 219 so as to lift the shearing blades 214 for the resetting thereof. In the lifting movement of the collar 215 by the resetting lever 22 which is formed with a bifurcated forward end 224 the said collar 215 is engaged by a latch arm 225 which is pivoted at 226 to the back of the plate 210, and this latch arm 225 is engaged by the trip extension 223 on the forward movement of the bail 71 for the release of said arm 225 to free the collar 215 for rendering the spring 219 active to lower the shearing blades 214 for the severing of the stamps. It will, of course, be seen that when the bail moves forwardly the trip extension 223 clears the resetting lever 222 so that the same will not be disturbed or be operated until the bail is automatically moved rearwardly, as hereinbefore set forth.

It is of course to be understood that this 130

shearing device is only to be used in the machine when the latter is constructed with a modified form of stamp ejecting or delivering mechanism hereinafter fully described for the reason that in the stamp ejecting or delivering mechanism hereinbefore described, when actuated on the deposit of a twenty-five cent coin or a fifty cent coin in the carrier, the gears 92 rotate in a step by step manner a quarter turn each so that six and a quarter stamps of the strip are ejected from the machine, and should the severing device be employed it would effect the cutting of stamps in two.

The indicator mechanism comprises pairs of swinging arms 227 and 228, respectively, which are fixed to shafts 229 journaled in bearings 230 on the platform 38, which latter is provided with openings 231 directly beneath the paths of the stamp strips 126 when traveling over certain of the guide rolls 127, while connected to these shafts 229 are the shanks 232 of shoes 233 which rest upon the strips 126 directly over the openings 231 in the platform 38 and upon the arms 227 and 228 are shutters 234 each having a slot 235, and these slots are adapted to register with certain of the slots 14 in the bar or plate 13 on the top 12 of the casing A so as to permit the introduction of coins therethrough. On the shutters 234 forwardly of the slots 235 therein is printed or otherwise marked the word "Empty," as at 236. When the strips 126 either become broken or the entire strips have been fed from the machine the openings 231 are uncovered and the shoes 233 drop through the said openings, thereby moving the arms 227 and 228 which shifts the shutters 234, thus moving the slots 235 therein out of register with the slots 14 in the bar or plate 13, thus closing the same and at the same time bringing the indicia "Empty," as at 236, in view through the peep openings 237 in the top 12 of the casing A so that one will have knowledge of the fact that the machine is empty of stamps.

Connected to the arm 179 is a pull rod 238 which is also pivoted to a crank 239 fixed to a stud shaft 240 mounted in a bearing 241 on the back of the frame 10 of the casing A, and to this stud shaft is fixed an arm 242 which carries a shutter 243 provided with a slot 244 and also having at one side of the slot the word "Empty," as at 245, the slot 244 being normally in registration with the depository slots for the delivering of coins to the coin changing mechanism to effect the operation thereof. Should the coin changing mechanism be empty of coins the weight beam 179 will be rocked under the action of the weight 182 to bring the rear end of said beam to lowermost position and thus pull upon the rod 238, which moves the arm 242 in a position to shift the shutter

243, whereby the slot 244 is thrown out of registration with the slots 14 in the bar 13 on the top 12 of the casing A, thereby closing the slots 14 to prevent the insertion of coins within the machine and at the same time the word "Empty," as at 245, on the shutter 243, is brought in position to be viewed through the peep opening 246 in the top 12 of the casing A, thereby indicating that the coin changing mechanism is empty of coins.

When a sufficient number of coins has been deposited within the coin changing mechanism the beam 179 is overbalanced by the weight of the said coins and the shutter 243 is automatically thrown to a position for opening the slots 14 in the top of the casing so that coins may be deposited therein for receiving change in lieu thereof.

In Figs. 65 and 66 there is shown a slight modification of the feed gear construction of the stamp ejecting or delivery mechanism which comprises a large gear 247 adapted to be mounted at each side of the bracket 89 in place of the gear 92 and is similarly constructed with respect to the gear 92 with the exception that the internal shoulder 248 is provided at intervals with notches 249 therein which are of an increased number with respect to the notches 97 in the gear 92 and likewise the inner face of this gear carries a plurality of lugs 250 which are of increased number with respect to the lugs 94 on the gear 92. In other words, in this gear 247 there are five notches 249 and also five lugs 250 thereon in contradistinction to the four notches 97 and four lugs 94 respectively in and on the gear 92 so that the gear 247 will be operated by the feed mechanism of the stamp ejecting or delivering mechanism five successive times for the ejecting of five stamps on each movement of the gear 247, whereas on the successive movements of the gear 92 a quarter turn, by reason of the construction thereof, there will be ejected six stamps and a fraction thereof. With the modified form of gear mechanism just described there is employed the severing or cutting mechanism hereinbefore set forth.

The machine is adapted to receive strips 126 of one and two cent stamps which are wound upon the reels 125 placed upon the ends of the shaft 91 between washers 251 which are located at opposite sides of the said reels and loosely surround the shaft 91, and working against the outermost washers are the coiled expansion springs 129 which are detachably held on the shaft by means of the cotter pins 128 which are passed through suitable openings in the ends of the shaft, and these pins and the springs are engaged with hanger chains 254 which are secured to the horizontal side bars in the frame 10 of the casing A of the machine, so that when the springs and cotter pins are removed

- from the shaft they will not become displaced or lost and on the removal of these pins and the springs the reels can be readily detached from the shafts. The strips are trained about the guide rolls 127, with the ends arranged between the feed and guide rollers 27 and 28 for the automatic ejecting of the strips in the operation of the machine in a manner presently described.
- 5 10 On the deposit of a single coin of one cent valuation or denomination within one of the slots 14 which, by the indicia upon the label 21 in the holder 20, is designated for receiving such coin, the latter will gravitate in the 15 chute 54 in the housing 51 of the carrier and will pass into the passage 56 and become blocked by the stop 79 so that the hole 58 in the housing 51 will be closed and the coin will lie in the path of the short finger 81 on 20 the fork 59. On movement of the carrier forwardly by pulling upon the handle 72 which projects exteriorly of the casing A through a slot 73 the coin will be brought into engagement with the short finger 81, 25 causing the fork 59 to be thrown to the left hand side of the machine and also to become advanced for the engagement of its limb at the left hand side of the machine, with the pin on the feed dog 41 at this side of the machine so that the dog will be advanced, and during such movement the latch pawl 40 adjacent thereto will become automatically 30 disengaged from the latch wheel 43 and the feed dog 41 engaged with the feed wheel 44 for 35 the turning of the feed roller 27 and also the guide roller 28, causing the ejecting of a single stamp through the stamp opening 15 in the front of the casing A, which stamp is of a valuation corresponding to the denomination of coin inserted in the machine.
- 40 On the return movement of the housing 51 of the carrier the stop 79 is tripped to open position by the tip 85 of the spring 84 so that the coin deposited within the carrier 45 will be freed therefrom for the dropping thereof into the trough 86, whence the said coin will fall into the column or cylinder 148 of the coin changing mechanism. Upon the return movement of the carrier the fork 59 50 moves rearwardly and the wings 69 thereon bring it to a neutral position for disengagement from the pins 67 and the springs will act upon the latch pawl 40 and feed dog 41 at the left hand side of the machine to lock 55 the feed roller 27 and retract the said feed dog to normal position.
- 56 When two coins of the same valuation or denomination, namely, two one cent pieces or pennies, are inserted in the proper slots in 60 the bar or plate 13 at the top of the casing A of the machine, the said coins gravitate in the chute 54 into the respective passages 55' and 56 and are blocked therein by the stop 79 to position the coins for closing both holes

57 and 58 so that upon movement of the carrier forwardly these coins will act upon both fingers 80 and 81 of the fork 59, thus effecting the movement thereof to the right hand side of the machine for the engagement of the notch 66 with the pin 68 on the feed dog 41 at the right hand side of the machine and upon further forward movement of the carrier the feed dog is advanced and simultaneously therewith the latch pawl 40 is disengaged from the latch wheel 43, while the feed dog 41 engages with the feed wheel 44, causing the same to turn one tooth, which rotates the feed and guide rollers 27 and 28 for the ejecting of a single stamp of a valuation in accordance with the value or denominations of the two coins inserted within the machine.

65 When the carrier moves rearwardly the coins are automatically released in the same for the dropping thereof into the trough 86 whence the coins gravitate into the coin column or cylinder 148 of the coin changing mechanism and also the fork 59 becomes adjusted to neutral position. The stop 79, after it has been momentarily tripped by the tip 85 of the spring 84, is released therefrom by the swell 87 so that the stop will assume a normal position to block the proper coins inserted within the housing 51 of the carrier for the next operation of the machine.

80 When a coin having a twenty-five cent valuation is deposited within the chute 55 in the housing 51 of the carrier it gravitates to a position for closing the hole in the housing 51 at the left hand side of the machine so that the coin will be in the path of the plunger 100 at the left hand side of the machine whereby, on the forward movement of the carrier, the said plunger will be advanced and simultaneously therewith the latch pawl 104 adjacent thereto will unlock the gear 92 and the feed dog 101 will engage one of the lugs 94 on the gear 92 for 100 rotating the same a limited distance and by 105 the connection of the gear with the feed roller 27 the latter will cause the ejecting of six stamps and a fraction thereof from the machine during a single forward movement of the plunger 100. The coin, on the 110 return movement of the carrier, is retained within the latter by the stop 123 until the gear 92, from its initial starting point, has made a complete revolution so that twenty-five stamps of an aggregate valuation equal 115 to the value or denomination of the coin deposited will be ejected from the machine and thereafter the said coin is released from the carrier automatically by the trip dog 134, which is raised into the path of the 120 said stop 123 by the lifting member 140, which is actuated by the pin 142 on the gear 92 to raise the lever 137 during the rotation

125

of the gear 92, and the said coin is deposited within the machine. Should it be desired to receive twenty-five stamps of a two cent denomination a coin having a fifty cent valuation is inserted in the chute 55 in the carrier and this coin will close the hole 122 at the right hand side of the machine, whereupon the coin ejecting or delivering mechanism will be operated at this side of the machine for the delivering of the above named number of stamps therefrom. The said mechanism at the right hand side of the machine is operated in the identical manner hereinbefore described with respect to the operation of the gear 92 at the left hand side of the machine. When the depositor requires change of the one cent or penny denomination, on inserting a coin of a five cent denomination in the slot 53 of the carrier and the latter is advanced or moved forwardly the plunger 158 at the right hand side of the machine is operated, which effects the actuation of the coin changing mechanism so that five coins of the one cent or penny denomination are ejected from the machine. On the deposit of a coin of the ten cent or dime denomination it will effect the actuation of the plunger 159 at the left hand side of the machine when the carrier is advanced or moved forwardly and the coin changing mechanism is automatically adjusted and the ejecting from the machine of ten coins of the one cent or penny denomination is successfully effected, thereby giving to the depositor the change so that the stamp ejecting or delivering mechanism can be successfully operated either for the delivery of stamps of the one cent denomination or the two cent denomination from the machine.

It will be impossible to fraudulently manipulate the machine by the deposit of spurious coins therein or otherwise as the stamp ejecting and delivering mechanism is automatically locked and likewise the coin changing mechanism is controlled to eliminate the fraudulent operation thereof. Also it will be impossible to insert coins within the machine when there are no stamps therein or when the coin changing mechanism is empty of coins for the supplying of change to the depositor or the number of coins within the said coin changing mechanism is less than the amount deposited within the machine. Should the number of coins within the coin changing mechanism be of a value less than that of the coin for which change is desired said coin is returned to the depositor and the coin changing mechanism will not operate until the number of coins is present therein to give the correct change to the depositor.

Should slugs or spurious coins be deposited within the carrier the same are returned

to the depositor in a manner as hereinbefore described so that these coins cannot possibly be used for the successful operation of the machine.

Mounted upon the rear face of the housing 51 near the wider end thereof is a cross bar 255 which has arranged therein in any suitable manner at the point of each slot in said housing a permanent magnet 256, the wall of the housing next to the magnet 256 being cut away so that the said magnet will serve as a coin detector, and on the deposit in said slot of a spurious or non-precious metal slug or foreign coin the magnet will attract the same through the opening 257 in the back of the housing 51 for its discharge exteriorly of said housing, thereby preventing such coin from passing downwardly into the housing or the choking of the slots therein.

The housing 51 at the point of the opening 83 has formed in the wall of said opening a nib 259 so that nothing larger than the size of a five cents or nickel coin can pass the same when deposited within the passage 55 in said housing.

It will of course be obvious that the nibs 88 and 259 in the chutes or slots serve to assort the coins of smaller diameter and also to let coins or slugs pass which are of the same size or diameter but less in thickness than the coin of proper denomination and thereby avoid fraudulent operation of the machine.

From the foregoing description, taken in connection with the accompanying drawings, the construction and operation of my stamp vending machine will be readily apparent and, therefore, a more extended explanation has been omitted.

Having thus described my invention, I claim:

1. A machine of the character described comprising a frame, stamp ejecting mechanism supported therein, mechanism for supplying strip stamps to the stamp ejecting mechanism, means forming a movable coin receiver and carrier and rendered operative upon the deposit of one or a plurality of coins therein for actuating the ejecting mechanism for the delivery of a stamp or stamps having valuations corresponding to the denomination of the coin or coins deposited, coin ejecting mechanism, devices automatically set on movement of the carrier by the coin or coins therein to automatically adjust the coin ejecting mechanism for regulating the feed thereof, and means located in relation to the carrier for receiving and assorting the coins when discharged thereby.

2. A machine of the character described comprising a frame, stamp ejecting mechanism supported therein, mechanism for supplying strip stamps to the stamp ejecting

mechanism, means forming a movable coin receiver and carrier and rendered operative upon the deposit of one or a plurality of coins therein for actuating the ejecting mechanism for the delivery of a stamp or stamps having valuations corresponding to the denomination of the coin or coins deposited, coin ejecting mechanism, and devices automatically set on movement of the carrier by the coin or coins therein to automatically adjust the coin ejecting mechanism for regulating the feed thereof.

3. A machine of the character described comprising a frame, stamp ejecting mechanism supported therein, mechanism for supplying strip stamps to the stamp ejecting mechanism, means forming a movable coin receiver and carrier and rendered operative upon the deposit of one or a plurality of coins therein for actuating the ejecting mechanism for the delivery of a stamp or stamps having valuations corresponding to the denomination of the coin or coins deposited, coin ejecting mechanism, devices automatically set on movement of the carrier by the coin or coins therein to automatically adjust the coin ejecting mechanism for regulating the feed thereof, and mechanism co-operative with the carrier to lock the same against reverse movement between the initial and completed movements thereof.

4. A machine of the character described comprising a frame, stamp ejecting mechanism supported therein, mechanism for supplying strip stamps to the stamp ejecting mechanism, means forming a movable coin receiver and carrier and rendered operative upon the deposit of one or a plurality of coins therein for actuating the ejecting mechanism for the delivery of a stamp or stamps having valuations corresponding to the denomination of the coin or coins deposited, coin ejecting mechanism, devices automatically set on movement of the carrier by the coin or coins therein to automatically adjust the coin ejecting mechanism for regulating the feed thereof, mechanism co-operative with the carrier to lock the same against reverse movement between the initial and completed movements thereof, coin arresters upon the carrier, and means for tripping the coin arresters at the instant of its completed return movement for the automatic deposit of the coin or coins.

5. A machine of the character described comprising a frame, stamp ejecting mechanism supported therein, mechanism for supplying strip stamps to the stamp ejecting mechanism, means forming a movable coin receiver and carrier and rendered operative upon the deposit of one or a plurality of coins therein for actuating the ejecting mechanism for the delivery of a stamp or stamps having valuations corresponding to the denomination of the coin or coins de-

posited, coin ejecting mechanism, devices automatically set on movement of the carrier by the coin or coins therein to automatically adjust the coin ejecting mechanism for regulating the feed thereof, mechanism co-operative with the carrier to lock the same against reverse movement between the initial and completed movements thereof, coin arresters upon the carrier, means for tripping the coin arresters at the instant of its completed return movement for the automatic deposit of the coin or coins, and means located in relation to the carrier for receiving and assorting the coins when discharged thereby.

6. A machine of the character described comprising a frame, stamp ejecting mechanism supported therein, mechanism for supplying strip stamps to the stamp ejecting mechanism, means forming a movable coin receiver and carrier and rendered operative upon the deposit of one or a plurality of coins therein for actuating the ejecting mechanism for the delivery of a stamp or stamps having valuations corresponding to the denomination of the coin or coins deposited, coin ejecting mechanism, devices automatically set on movement of the carrier by the coin or coins therein to automatically adjust the coin ejecting mechanism for regulating the feed thereof, mechanism co-operative with the carrier to lock the same against reverse movement between the initial and completed movements thereof, coin arresters upon the carrier, means for tripping the coin arresters at the instant of their completed return movement for the automatic deposit of the coin or coins, means located in relation to the carrier for receiving and assorting the coins when discharged thereby, and coin changing mechanism within the frame and operated when a coin or coins have been deposited within the carrier and the latter actuated.

7. A machine of the character described comprising a frame, stamp ejecting mechanism supported therein, mechanism for supplying strip stamps to the stamp ejecting mechanism, means forming a movable coin receiver and carrier and rendered operative upon the deposit of one or a plurality of coins therein for actuating the ejecting mechanism for the delivery of a stamp or stamps having valuations corresponding to the denomination of the coin or coins deposited, coin ejecting mechanism, devices automatically set on movement of the carrier by the coin or coins therein to automatically adjust the coin ejecting mechanism for regulating the feed thereof, mechanism co-active with the carrier to lock the same against reverse movement between the initial and completed movements thereof, coin arresters upon the carrier, means for tripping the coin arresters at the instant of their

completed return movement for the automatic deposit of the coin or coins, means located in relation to the carrier for receiving and assorting the coins when discharged thereby, coin changing mechanism within the frame and operated when a coin or coins have been deposited within the carrier and the latter actuated, and means for automatically setting the coin changing mechanism for operation when a predetermined number 5 of coins have been deposited therein.

8. A machine of the character described comprising stamp delivering mechanism, latch members controlling said mechanism, feed members for operating said mechanism, 15 a movably supported coin carrier having a plurality of chutes communicative from the exterior of said carrier, and an actuating fork mounted for automatic adjustment by a coin or coins inserted within the chute or chutes in the carrier for automatically operating 20 the feed member or members on movement of the carrier.

9. A machine of the character described comprising stamp delivering mechanism, latch members controlling said mechanism, feed members for operating said mechanism, a movably supported coin carrier having a plurality of chutes communicative from the 30 exterior of said carrier, an actuating fork mounted for automatic adjustment by a coin or coins inserted within the chute or chutes in the carrier for automatically operating the feed member or members on movement 35 of the carrier, and means on the locking and feed members for coöperation with each other to automatically release the locking members on movement of the feed members.

10. A machine of the character described comprising stamp delivering mechanism, 40 latch members controlling said mechanism, feed members for operating said mechanism, a movably supported coin carrier having a plurality of chutes communicative from the exterior of said carrier, an actuating fork mounted for automatic adjustment by a coin or coins inserted within the chute or chutes in the carrier for automatically operating the feed member or members on movement 45 of the carrier, means on the locking and feed members for coöperation with each other to automatically release the locking members on movement of the feed members, and means projecting exteriorly of the machine for moving the carrier.

11. A machine of the character described comprising stamp delivering mechanism, latch members controlling said mechanism, feed members for operating said mechanism, 50 a movably supported coin carrier having a plurality of chutes communicative from the exterior of said carrier, an actuating fork mounted for automatic adjustment by a coin or coins inserted within the chute or chutes in the carrier for automatically operating 55 the feed member or members on movement of the carrier, means on the locking and feed members for coöperation with each other to automatically release the locking members on movement of the feed members, and means projecting exteriorly of the machine for moving the carrier.

the feed member or members on movement of the carrier, means on the locking and feed members for coöperation with each other to automatically release the locking members on movement of the feed members, means 70 projecting exteriorly of the machine for moving the carrier, and means for locking the carrier against return movement between the initial and completed forward movements thereof.

12. A machine of the character described comprising stamp delivering mechanism, latch members controlling said mechanism, feed members for operating said mechanism, a movably supported coin carrier having a 80 plurality of chutes communicative from the exterior of said carrier, an actuating fork mounted for automatic adjustment by a coin or coins inserted within the chute or chutes in the carrier for automatically operating 85 the feed member or members on movement of the carrier, means on the locking and feed members for coöperation with each other to automatically release the locking members on movement of the feed members, means 90 projecting exteriorly of the machine for moving the carrier, means for locking the carrier against return movement between the initial and completed forward movements thereof, and means for supplying strip 95 stamps to the ejecting mechanism.

13. A machine of the character described comprising stamp delivering mechanism, latch members controlling said mechanism, feed members for operating said mechanism, 100 a movably supported coin carrier having a plurality of chutes communicative from the exterior of said carrier, an actuating fork mounted for automatic adjustment by a coin or coins inserted within the chute or chutes 105 in the carrier for automatically operating the feed member or members on movement of the carrier, means on the locking and feed members for coöperation with each other to automatically release the locking members on 110 movement of the feed members, means projecting exteriorly of the machine for moving the carrier, means for locking the carrier against return movement between the initial and completed forward movements thereof, 115 means for supplying strip stamps to the ejecting mechanism, and counting devices co-operating with the ejecting mechanism.

14. A machine of the character described comprising stamp delivering mechanism, latch members controlling said mechanism, feed members for operating said mechanism, a movably supported coin carrier having a 120 plurality of chutes communicative from the exterior of said carrier, an actuating fork 125 mounted for automatic adjustment by a coin or coins inserted within the chute or chutes in the carrier for automatically operating the feed member or members on movement of the carrier, means on the locking and feed 130 members for coöperation with each other to automatically release the locking members on movement of the feed members, and means projecting exteriorly of the machine for moving the carrier.

members for coöperation with each other to automatically release the locking members on movement of the feed members, means projecting exteriorly of the machine for 5 moving the carrier, means for locking the carrier against return movement between the initial and completed forward movements thereof, means for supplying strip stamps to the ejecting mechanism, counting devices co- 10 operating with the ejecting mechanism, and coin changing mechanism rendered operative upon deposit of a coin or coins within a certain chute or chutes in the carrier.

15. A machine of the character described comprising stamp delivering mechanism, latch members controlling said mechanism, feed members for operating said mechanism, a movably supported coin carrier having a plurality of chutes communicative from the 20 exterior of said carrier, an actuating fork mounted for automatic adjustment by a coin or coins inserted within the chute or chutes in the carrier for automatically operating the feed member or members on movement of 25 the carrier, means on the locking and feed members for coöperation with each other to automatically release the locking members on movement of the feed members, means projecting exteriorly of the machine for 30 moving the carrier, means for locking the carrier against return movement between the initial and completed forward movements thereof, means for supplying strip stamps to the ejecting mechanism, counting devices co- 35 operating with the ejecting mechanism, coin changing mechanism rendered operative upon deposit of a coin or coins within a certain chute or chutes in the carrier, and mechanism for rendering the coin changing 40 mechanism inoperative when empty.

16. A machine of the character described comprising stamp delivering mechanism, latch members controlling said mechanism, feed members for operating said mechanism, 45 a movably supported coin carrier having a plurality of chutes communicative from the exterior of said carrier, an actuating fork mounted for automatic adjustment by a coin or coins inserted within the chute or chutes in the carrier for automatically operating the feed member or members on movement 50 of the carrier, means on the locking and feed members for coöperation with each other to automatically release the locking members 55 on movement of the feed members, means projecting exteriorly of the machine for moving the carrier, means for locking the carrier against return movement between the initial and completed forward movements 60 thereof, means for supplying strip stamps to the ejecting mechanism, counting devices co-operating with the ejecting mechanism, coin changing mechanism rendered operative upon deposit of a coin or coins within a certain chute or chutes in the carrier, mecha- 65

nism for rendering the coin changing mechanism inoperative when empty, and trip means for arresting the coins deposited within the carrier for operating the ejecting and coin changing mechanisms and also for 70 releasing said coins subsequent thereto.

17. A machine of the character described comprising stamp delivering mechanism, latch members controlling said mechanism, feed members for operating said mechanism, a movably supported coin carrier having a plurality of chutes communicative from the exterior of said carrier, an actuating fork mounted for automatic adjustment by a coin or coins inserted within the chute 75 or chutes in the carrier for automatically operating the feed member or members on movement of the carrier, means on the locking and feed members for coöperation with each other to automatically release the locking members on movement of the feed members, means projected exteriorly of the machine for moving the carrier, means for locking the carrier against return movement between the initial and completed forward 80 movements thereof, means for supplying strip stamps to the ejecting mechanism, counting devices coöperating with the ejecting mechanism, coin changing mechanism rendered operative upon deposit of a coin or 85 coins within a certain chute or chutes in the carrier, mechanism for rendering the coin changing mechanism inoperative when empty, trip means for arresting the coins deposited within the carrier for operating the ejecting and coin changing mechanisms and also for releasing said coins subsequent thereto, and coin assorting mechanism for receiving the released coins and distributing the same within the machine.

18. In a machine of the character described, mechanism for delivering merchandise in strip form, a movable coin carrier, and means rendered operative upon the deposit of different denominations of coins 90 within the carrier for regulating the delivery mechanism and operating the same for the ejection of a length of the strip having a valuation corresponding to the denomination of the coin or coins deposited 95 within the carrier.

19. In a machine of the character described, mechanism for delivering merchandise in strip form, a movable coin carrier, means rendered operative upon the deposit 100 of different denominations of coins within the carrier for regulating the delivery mechanism and operating the same for the ejection of a length of the strip having a valuation corresponding to the denomination of the coin or coins deposited within the carrier, and means for locking the carrier against backward movement upon initially moving the same until it reaches its completed forward movement.

20. In a machine of the character described, mechanism for delivering merchandise in strip form, a movable coin carrier, means rendered operative upon the deposit 5 of different denominations of coins within the carrier for regulating the delivery mechanism and operating the same for the ejection of a length of the strip having a valuation corresponding to the valuation of 10 the coin or coins deposited within the carrier, means for locking the carrier against backward movement upon initially moving the same until it reaches its completed forward movement, and means for distributing 15 the coins deposited within the carrier.

21. In a machine of the character described, mechanism for delivering merchandise in strip form, a movable coin carrier, means rendered operative upon the deposit 20 of different denominations of coins within the carrier for regulating the delivery mechanism and operating the same for the ejection of a length of the strip having a valuation corresponding to the denomination 25 of the coin or coins deposited within the carrier, means for locking the carrier against backward movement upon initially moving the same until it reaches its completed forward movement, means for distributing the 30 coins deposited within the carrier, and means for releasing the coins in the carrier after operating the ejecting mechanism.

22. In a machine of the character described, mechanism for delivering merchandise in strip form, a movable coin carrier, means controlled by different denominations 35 of coins deposited within the carrier for regulating the delivery mechanism and operating the same for the ejection of a length 40 of the strip having a valuation corresponding to the denomination of the coin or coins deposited within the carrier, means for locking the carrier against backward movement upon initially moving the same until it reaches its completed forward movement, means for distributing coins deposited within 45 the carrier, means for releasing the coins in the carrier after operating the ejecting mechanism, and a coin trough for receiving 50 the assorted coins from the distributing means.

23. In a machine of the character described, mechanism for delivering merchandise in strip form, a movable carrier, means 55 rendered operative upon the deposit of different denominations of coins within the carrier for regulating the delivery mechanism and operating the same for the ejection of a length of the strip having a valuation 60 corresponding to the denomination of the coin or coins deposited within the carrier, means for locking the carrier against backward movement upon initially moving the same until it reaches its completed forward 65 movement, means for distributing coins de-

posited within the carrier, means for releasing the coins in the carrier after operating the ejecting mechanism, a coin trough for receiving the assorted coins from the distributing means, and coin changing mechanism 70 rendered operative upon the deposit of a coin or coins within a certain chute or chutes in the carrier.

24. In a machine of the character described, mechanism for delivering merchandise in strip form, a movable coin carrier, means rendered operative upon the deposit 75 of different denominations of coins within the carrier for regulating the delivery mechanism and operating the same for the ejection of a length of the strip having a valuation corresponding to the denomination of the coin or coins within the carrier, means for locking the carrier against backward movement upon initially moving the same until 80 it reaches its completed forward movement, means for distributing coins deposited within the carrier, means for releasing the coins in the carrier after operating the ejecting mechanism, a coin trough for receiving the 85 assorted coins from the distributing means, coin changing mechanism rendered operative upon the deposit of a coin or coins within a certain chute or chutes in the carrier, means for ejecting spurious coins deposited within 90 the carrier.

25. In a machine of the character described, mechanism for delivering merchandise in strip form, a movable coin carrier, means rendered operative upon the deposit 100 of different denominations of coins within the carrier for regulating the delivery mechanism and operating the same for the ejection of a length of the strip having a valuation corresponding to the denomination of 105 the coin or coins deposited within the carrier, means for locking the carrier against backward movement upon initially moving the same until it reaches its completed forward movement, means for distributing coins 110 deposited within the carrier, means for releasing the coins in the carrier after operating the ejecting mechanism, a coin trough for receiving the assorted coins from the distributing means, coin changing mechanism 115 rendered operative upon the deposit of a coin or coins within a certain chute or chutes in the carrier, means for ejecting spurious coins deposited within the carrier, and means for operating the carrier. 120

26. In a machine of the character described, mechanism for delivering merchandise in strip form, a movable coin carrier, means rendered operative upon the deposit 125 of different denominations of coins within the carrier for regulating the delivery mechanism and operating the same for the ejection of a length of the strip having a valuation corresponding to the denomination of the coin or coins deposited within the car- 130

- rier, means for locking the carrier against backward movement upon initially moving the same until it reaches its completed forward movement, means for distributing coins deposited within the carrier, means for releasing the coins in the carrier after operating the ejecting mechanism, a coin trough for receiving the assorted coins from the distributing means, coin changing mechanism rendered operative upon the deposit of a coin or coins within a certain chute or chutes in the carrier, means for ejecting spurious coins deposited within the carrier, means for operating the carrier, and means for counting the articles in the strip delivered.
27. In a machine of the character described, mechanism for delivering merchandise in strip form, a movable coin carrier, means rendered operative upon the deposit of different denominations of coins within the carrier for regulating the delivery mechanism and operating the same for the ejection of a length of the strip having a valuation corresponding to the denomination of the coin or coins deposited within the carrier, means for locking the carrier against backward movement upon initially moving the same until it reaches its completed forward movement, means for distributing coins deposited within the carrier, means for releasing the coins in the carrier after operating the ejecting mechanism, a coin trough for receiving the assorted coins from the distributing means, coin changing mechanism rendered operative upon the deposit of a coin or coins within a certain chute or chutes in the carrier, means for ejecting spurious coins deposited within the carrier, means for operating the carrier, means for counting the articles in the strip delivered, and means for setting the coin changing mechanism to render the same operative or inoperative according to the number of coins therein.
45. 28. In a machine of the character described, mechanism for delivering merchandise in strip form, a movable coin carrier, means rendered operative upon the deposit of different denominations of coins within the carrier for regulating the delivery mechanism and operating the same for the ejection of a length of the strip having a valuation corresponding to the denomination of the coin or coins deposited within the carrier, means for locking the carrier against backward movement upon initially moving the same until it reaches its completed forward movement, means for distributing coins deposited within the carrier, means for releasing the coins in the carrier after operating the ejecting mechanism, a coin trough for receiving the assorted coins from the distributing means, coin changing mechanism rendered operative upon the deposit of a coin or coins within a certain chute or chutes in the carrier, means for ejecting spurious coins deposited within the carrier, means for operating the carrier, means for counting the articles in the strip delivered, means for setting the coin changing mechanism to render the same operative or inoperative according to the number of coins therein, means for conducting coins of a predetermined denomination to the coin changing mechanism from the carrier, and means for delivering an excess number of coins from the coin changing mechanism to the coin trough.
50. 29. In a machine of the character described, mechanism for delivering merchandise in strip form, a movable coin carrier, means rendered operative upon the deposit of different denominations of coins within the carrier for regulating the delivery mechanism and operating the same for the ejection of a length of the strip having a valuation corresponding to the denomination of the coin or coins deposited within the carrier, means for locking the carrier against backward movement upon initially moving the same until it reaches its completed forward movement, means for distributing coins deposited within the carrier, means for releasing the coins in the carrier after operating the ejecting mechanism, a coin trough for receiving the assorted coins from the distributing means, coin changing mechanism rendered operative upon the deposit of a coin or coins within a certain chute or chutes in the carrier, means for ejecting spurious coins deposited within the carrier, means for operating the carrier, means for counting the articles in the strip delivered, means for setting the coin changing mechanism to render the same operative or inoperative according to the number of coins therein, means for conducting coins of a predetermined denomination to the coin changing mechanism from the carrier, and means for delivering an excess number of coins from the coin changing mechanism to the coin trough.
55. 30. In a machine of the character described, mechanism for delivering merchandise in strip form, a movable coin carrier, means rendered operative upon the deposit of different denominations of coins within the carrier for regulating the delivery mechanism and operating the same for the ejection of a length of the strip having a valuation corresponding to the denomination of the coin or coins deposited within the carrier, means for locking the carrier against backward movement upon initially moving the same until it reaches its completed forward movement, means for distributing coins deposited within the carrier, means for releasing the coins in the carrier after operating the ejecting mechanism, a coin trough for receiving the assorted coins from the distributing means, coin changing mechanism rendered operative upon the deposit of a coin or coins within a certain chute or chutes in the carrier, means for ejecting spurious coins deposited within the carrier, means for operating the carrier, means for counting the articles in the strip delivered, means for setting the coin changing mechanism to render the same operative or inoperative according to the number of coins therein, means for conducting coins of a predetermined denomination to the coin changing mechanism from the carrier, and means for delivering an excess number of coins from the coin changing mechanism to the coin trough.

tributing means, coin changing mechanism rendered operative upon the deposit of a coin or coins within a certain chute or chutes in the carrier, means for ejecting spurious coins deposited within the carrier, means for operating the carrier, means for counting the articles in the strip delivered, means for setting the coin changing mechanism to render the same operative or inoperative according to the number of coins therein, means for conducting coins of a predetermined denomination to the coin changing mechanism from the carrier, and means for delivering an excess number of coins from the coin changing mechanism to the coin trough and also from the carrier.

31. In a machine of the character described, mechanism for delivering merchandise in strip form, a movable coin carrier, means rendered operative upon the deposit of different denominations of coins within the carrier for regulating the delivery mechanism and operating the same for the ejection of a length of the strip having a valuation corresponding to the denomination of the coin or coins deposited within the carrier, means for locking the carrier against backward movement upon initially moving the same until it reaches its completed forward movement, means for distributing coins deposited within the carrier, means for releasing the coins in the carrier after operating the ejecting mechanism, a coin trough for receiving the assorted coins from the distributing means, coin changing mechanism rendered operative upon the deposit of a coin or coins within a certain chute or chutes in the carrier, means for ejecting spurious coins deposited within the carrier, means for operating the carrier, means for counting the articles in the strip delivered, means for setting the coin changing mechanism to render the same operative or inoperative according to the number of coins therein, means for conducting coins of a predetermined denomination to the coin changing mechanism from the carrier, and means for delivering an excess number of coins from the coin changing mechanism to the coin trough and also from the carrier, and mechanism automatically set by the coin or coins deposited within the carrier for regulating the feed of said strip to the delivery mechanism.

32. In a machine of the character described, mechanism for delivering merchandise in strip form, a movable coin carrier, means rendered operative upon the deposit of different denominations of coins within the carrier for regulating the delivery mechanism and operating the same for the ejection of a length of the strip having a valuation corresponding to the denomination of the coin or coins deposited within the carrier, means for locking the carrier

against backward movement upon initially moving the same until it reaches its completed forward movement, means for distributing coins deposited within the carrier, means for releasing the coins in the carrier after operating the ejecting mechanism, a coin trough for receiving the assorted coins from the distributing means, coin changing mechanism rendered operative upon the deposit of a coin or coins within a certain chute or chutes in the carrier, means for ejecting spurious coins deposited within the carrier, means for operating the carrier, means for counting the articles in the strip delivered, means for setting the coin changing mechanism to render the same operative or inoperative according to the number of coins therein, means for conducting coins of a predetermined denomination to the coin changing mechanism from the carrier, means for delivering an excess number of coins from the coin changing mechanism to the coin trough and also from the carrier, mechanism automatically set by the coin or coins deposited within the carrier for regulating the feed of said strip to the delivery mechanism, and means for supplying said strip to said delivery mechanism.

33. In a machine of the character described, mechanism for delivering merchandise in strip form, a movable coin carrier, means rendered operative upon the deposit of different denominations of coins within the carrier for regulating the delivery mechanism and operating the same for the ejection of a length of the strip having a valuation corresponding to the denomination of the coin or coins deposited within the carrier, means for locking the carrier against backward movement upon initially moving the same until it reaches its completed forward movement, means for distributing coins deposited within the carrier, means for releasing the coins in the carrier after operating the ejecting mechanism, a coin trough for receiving the assorted coins from the distributing means, coin changing mechanism rendered operative upon the deposit of a coin or coins within a certain chute or chutes in the carrier, means for ejecting spurious coins deposited within the carrier, means for operating the carrier, means for counting the articles in the strip delivered, means for setting the coin changing mechanism to render the same operative or inoperative according to the number of coins therein, means for conducting coins of a predetermined denomination to the coin changing mechanism from the carrier, means for delivering an excess number of coins from the coin changing mechanism to the coin trough and also from the carrier, mechanism automatically set by the coin or coins deposited within the carrier for regulating the feed of said strip to the delivery mechanism.

the feed of said strip to the delivery mechanism, means for supplying said strip to said delivery mechanism, and severing means operated by the means for moving the carrier.

34. In a machine of the character described, mechanism for delivering merchandise in strip form, a movable coin carrier, means rendered operative upon the deposit of different denominations of coins within the carrier for regulating the delivery mechanism and operating the same for the ejection of a length of the strip having a valuation corresponding to the denomination of the coin or coins deposited within the carrier, means for locking the carrier against backward movement upon initially moving the same until it reaches its completed forward movement, means for distributing coins deposited within the carrier, means for releasing the coins in the carrier after operating the ejecting mechanism, a coin trough for receiving the assorted coins from the distributing means, coin changing mechanism rendered operative upon the deposit of a coin or coins within a certain chute or chutes in the carrier, means for ejecting spurious coins deposited within the carrier, means for operating the carrier, means for counting the articles in the strip delivered, means for setting the coin changing mechanism to render the same operative or inoperative according to the number of coins therein, means for conducting coins of a predetermined denomination to the coin changing mechanism from the carrier, means for delivering an excess number of coins from the coin changing mechanism to the coin trough and also from the carrier, mechanism automatically set by the coin or coins deposited within the carrier for regulating the feed of said strip to the delivery mechanism, means for supplying said strip to said delivery mechanism, severing means operated by the means for moving the carrier, and mechanism controlled by the supply means for closing the communications to the chutes in the carrier when said strip is exhausted.

35. In a machine of the character described, mechanism for delivering merchandise in strip form, a movable coin carrier, means rendered operative upon the deposit of different denominations of coins within the carrier for regulating the delivery mechanism and operating the same for the ejection of a length of the strip having a valuation corresponding to the denomination of the coin or coins deposited within the carrier, means for locking the carrier against backward movement upon initially moving the same until it reaches its completed forward movement, means for distributing coins in the carrier after operating the ejecting mechanism, a coin trough for

receiving the assorted coins from the distributing means, coin changing mechanism rendered operative upon the deposit of a coin or coins within a certain chute or chutes in the carrier, means for ejecting spurious coins deposited within the carrier, means for operating the carrier, means for counting the articles in the strip delivered, means for setting the coin changing mechanism to render the same operative or inoperative according to the number of coins therein, means for conducting coins of a predetermined denomination to the coin changing mechanism from the carrier, means for delivering an excess number of coins from the coin changing mechanism to the coin trough and also from the carrier, mechanism automatically set by the coin or coins deposited within the carrier for regulating the feed of said strip to the delivery mechanism, means for supplying said strip to said delivery mechanism, severing means operated by the means for moving the carrier, mechanism controlled by the supply means for closing the communications to the chutes in the carrier when said strip is exhausted, and mechanism controlled by the coin changing mechanism to indicate when the same is empty of coins and also for preventing the insertion of coins within the carrier for operating such coin changing mechanism

36. In a machine of the character described, mechanism for delivering merchandise in strip form, a movable coin carrier, means rendered operative upon the deposit of different denominations of coins within the carrier for regulating the delivery mechanism and operating the same for the ejection of a length of the strip having 105 a valuation corresponding to the denomination of the coin or coins deposited within the carrier, means for locking the carrier against backward movement upon initially moving the same until it reaches its completed forward movement, means for distributing coins deposited within the carrier, means for releasing the coins in the carrier after operating the ejecting mechanism, a coin trough for receiving the assorted coins 110 from the distributing means, coin changing mechanism rendered operative upon the deposit of a coin or coins within a certain chute or chutes in the carrier, means for ejecting spurious coins deposited within the 115 carrier, means for operating the carrier, means for counting the articles in the strip delivered, means for setting the coin changing mechanism to render the same operative or inoperative according to the number of 120 coins therein, means for conducting coins of a predetermined denomination to the coin changing mechanism from the carrier, means for delivering an excess number of 125 coins from the coin changing mechanism to 130

- the coin through and also from the carrier, mechanism automatically set by the coin or coins deposited within the carrier for regulating the feed of said strip to the delivery mechanism, means for supplying said strip to said delivery mechanism, severing means operated by the means for moving the carrier, mechanism controlled by the supply means for closing the communications to the chutes in the carrier when said strip is exhausted, mechanism controlled by the coin changing mechanism to indicate when the same is empty of coins and also for preventing the insertion of coins within the carrier for operating such coin changing mechanism, and means for returning to the depositor coins of improper denomination inserted in the carrier.
37. In a machine of the character described, mechanism for delivering merchandise in strip form, a movable carrier, means rendered operative upon the deposit of different denominations of coins within the carrier for regulating the delivery mechanism and operating the same for the ejection of a length of the strip having valuations corresponding to the denomination of the coin or coins deposited within the carrier, means for locking the carrier against backward movement upon initially moving the same until it reaches its completed forward movement, means for distributing coins deposited within the carrier, means for releasing the coins in the carrier after operating the ejecting mechanism, a coin trough for receiving the assorted coins from the distributing means, coin changing mechanism rendered operative upon the deposit of a coin or coins within a certain chute or chutes in the carrier, means for ejecting spurious coins deposited within the carrier, means for operating the carrier, means for counting the articles in the strip delivered, means for setting the coin changing mechanism to render the same operative or inoperative according to the number of coins therein, means for conducting coins of a predetermined denomination to the coin changing mechanism from the carrier, means for delivering an excess number of coins from the coin changing mechanism to the coin trough and also from the carrier, mechanism automatically set by the coin or coins deposited within the carrier for regulating the feed of said strip to the delivery mechanism, means for supplying said strip to said delivery mechanism, severing means operated by the means for moving the carrier, mechanism controlled by the supply means for closing the communications to the chutes in the carrier when said strip is exhausted, mechanism controlled by the coin changing mechanism to indicate when the same is empty of coins and also for preventing the insertion of
- coins within the carrier for operating such coin mechanism, means for returning to the depositor coins of improper denomination inserted in the carrier, and coin detectors carried by the carrier and adapted to discharge spurious coins therefrom when inserted therein.
38. A stamp vending machine having a movable carrier, means for operating the carrier, stamp ejecting means operated upon directly by a coin or coins deposited within the carrier when the latter is moved, means for supplying stamp strips to the ejecting mechanism, means operated on movement of the carrier for severing the stamps from the strip when ejected, coin changing mechanism, and means for delivering certain of the coins deposited within the carrier to the changing mechanism.
39. A stamp vending machine having a movable carrier, means for operating the carrier, stamp ejecting means operated upon directly by a coin or coins deposited within the carrier when the latter is moved, means for supplying stamp strips to the ejecting mechanism, means operated on movement of the carrier for severing the stamps from the strip when ejected, coin changing mechanism, means for delivering certain of the coins deposited within the carrier to the changing mechanism, and means for delivering excess coins from the changing mechanism interiorly of the casing.
40. A stamp vending machine having a movable carrier, stamp ejecting means operated upon directly by a coin or coins deposited within the carrier when the latter is moved, means for locking the ejecting mechanism against repeating action after the carrier has moved from normal position, means for releasing the coins from the carrier after actuating the ejecting mechanism, means for distributing the coins when released from the carrier, means for supplying stamp strips to the ejecting mechanism, and means operated on movement of the carrier for severing the stamps from the strip when ejected.
41. A stamp vending machine having a movable carrier, stamp ejecting means operated upon directly by a coin or coins deposited within the carrier when the latter is moved, means for locking the ejecting mechanism against repeating action after the carrier has moved from normal position, means for releasing the coins from the carrier after actuating the ejecting mechanism, means for distributing the coins when released from the carrier, means for supplying stamp strips to the ejecting mechanism, means operated on movement of the carrier for severing the stamps from the strip when ejected, and means for operating the carrier.
42. A stamp vending machine having a

movable carrier, stamp ejecting means operated upon directly by a coin or coins deposited within the carrier when the latter is moved, means for locking the ejecting mechanism against repeating action after the carrier has moved from normal position, means for releasing the coins from the carrier after actuating the ejecting mechanism, means for distributing the coins when released from the carrier, means for supplying stamp strips to the ejecting mechanism, means operated on movement of the carrier for severing the stamps from the strip when ejected, means for operating the carrier, and means for automatically returning the carrier to normal position.

43. A stamp vending machine having a movable carrier, stamp ejecting means operated upon directly by a coin or coins deposited within the carrier when the latter is moved, means for locking the ejecting mechanism against repeating action after the carrier has moved from normal position, means for releasing the coins from the carrier after actuating the ejecting mechanism, means for distributing the coins when released from the carrier, means for supplying stamp strips to the ejecting mechanism, means operated on movement of the carrier for severing the stamps from the strip when ejected, means for operating the carrier, means for automatically returning the carrier to normal position, coin changing mechanism, and means for delivering certain of the coins deposited within the carrier to the changing mechanism.

44. A stamp vending machine having a movable carrier, stamp ejecting means operated upon directly by a coin or coins deposited within the carrier when the latter is moved, means for locking the ejecting mechanism against repeating action after the carrier has moved from normal position, means for releasing the coins from the carrier after actuating the ejecting mechanism, means for distributing the coins when released from the carrier, means for supplying stamp strips to the ejecting mechanism, means operated on movement of the carrier for severing the stamps from the strip when ejected, means for operating the carrier, means for automatically returning the carrier to normal position, coin changing mechanism, means for delivering certain of the coins deposited within the carrier to the changing mechanism, and means for delivering excess coins from the changing mechanism interiorly of the casing.

45. A stamp vending machine having a movable carrier, stamp ejecting means operated upon directly by a coin or coins deposited within the carrier when the latter is moved, means for locking the ejecting mechanism against repeating action after the carrier has moved from normal position, means

for releasing the coins from the carrier after actuating the ejecting mechanism, means for distributing the coins when released from the carrier, means for supplying stamp strips to the ejecting mechanism, means operated on movement of the carrier for severing the stamps from the strip when ejected, means for operating the carrier, means for automatically returning the carrier to normal position, coin changing mechanism, means for delivering certain of the coins deposited within the carrier to the changing mechanism, means for delivering excess coins from the changing mechanism interiorly of the casing, and means for rendering the changing mechanism inactive when without a predetermined number of coins.

46. A stamp vending machine having a movable carrier, stamp ejecting means operated upon directly by a coin or coins deposited within the carrier when the latter is moved, means for locking the ejecting mechanism against repeating action after the carrier has moved from normal position, means for releasing the coins from the carrier after actuating the ejecting mechanism, means for distributing the coins when released from the carrier, means for supplying stamp strips to the ejecting mechanism, means operated on movement of the carrier for severing the stamps from the strip when ejected, means for operating the carrier, means for automatically returning the carrier to normal position, coin changing mechanism, means for delivering certain of the coins deposited within the carrier to the changing mechanism, means for delivering excess coins from the changing mechanism interiorly of the casing, means for rendering the changing mechanism inactive when without a predetermined number of coins, and means for returning coins from the changing mechanism when the latter is inactive.

47. A stamp vending machine having a movable carrier, stamp ejecting means operated upon directly by a coin or coins deposited within the carrier when the latter is moved, means for locking the ejecting mechanism against repeating action after the carrier has moved from normal position, means for releasing the coins from the carrier after actuating the ejecting mechanism, means for distributing the coins when released from the carrier, means for supplying stamp strips to the ejecting mechanism, means operated on movement of the carrier for severing the stamps from the strip when ejected, means for operating the carrier, means for automatically returning the carrier to normal position, coin changing mechanism, means for delivering certain of the coins deposited within the carrier to the changing mechanism, means for delivering excess coins from the changing mechanism interiorly of the casing, means for rendering the

changing mechanism inactive when without a predetermined number of coins, means for returning coins from the changing mechanism when the latter is inactive, and means 5 for preventing spurious coins from remaining in position in the carrier to actuate the ejecting mechanism.

48. A stamp vending machine having a movable carrier, means for operating the 10 carrier, stamp ejecting means operated upon directly by a coin or coins deposited within the carrier when the latter is moved, means for locking the ejecting mechanism against repeating action after the carrier has moved 15 from normal position, means for releasing the coins from the carrier after actuating the ejecting mechanism, means for distributing the coins when released from the carrier, means for supplying stamp strips to the 20 ejecting mechanism, means operated on movement of the carrier for severing the stamps from the strip when ejected, coin changing mechanism, means for rendering the changing mechanism inactive when 25 without a predetermined number of coins, means for returning the deposited coins from the changing mechanism when the latter is inactive, and means for detecting spurious coins and ejecting the same from 30 the carrier.

49. A stamp vending machine having a movable carrier, stamp ejecting means operated upon directly by a coin or coins deposited within the carrier when the latter is moved, means for locking the ejecting mechanism against repeating action after the carrier has moved from normal position, means for releasing the coins from the carrier after actuating the ejecting mechanism, means for distributing the coins when 35 released from the carrier, means for supplying stamp strips to the ejecting mechanism, means operated on movement of the carrier for severing the stamps from the strip when ejected, means for operating the carrier, means for automatically returning the carrier to normal position, coin changing mechanism, means for delivering certain of the coins deposited within the carrier to the 45 changing mechanism, means for delivering excess coins from the changing mechanism interiorly of the casing, means for rendering the changing mechanism inactive when without a predetermined number of coins, 50 means for returning the coins from the changing mechanism when the latter is inactive, and means for detecting spurious coins and ejecting the same from the carrier.

50. A stamp vending machine having a 60 movable carrier, means for operating the carrier, stamp ejecting means operated upon directly by a coin or coins deposited within the carrier when the latter is moved, means for locking the ejecting mechanism against 65 repeating action after the carrier has moved

from normal position, means for releasing the coins from the carrier after actuating the ejecting mechanism, means for distributing the coins when released from the carrier, means for supplying stamp strips to 70 the ejecting mechanism, means operated on movement of the carrier for severing the stamps from the strip when ejected, coin changing mechanism, and means for rendering the changing mechanism inactive when 75 without a predetermined number of coins.

51. A stamp vending machine having a movable carrier, means for operating the carrier, stamp ejecting means operated upon directly by a coin or coins deposited within 80 the carrier when the latter is moved, means for locking the ejecting mechanism against repeating action after the carrier has moved from normal position, means for releasing the coins from the carrier after actuating 85 the ejecting mechanism, means for distributing the coins when released from the carrier, means for supplying stamp strips to the ejecting mechanism, means operated on movement of the carrier for severing the 90 stamps from the strip when ejected, coin changing mechanism, means for rendering the changing mechanism inactive when without a predetermined number of coins, and means for returning the deposited coins 95 from the changing mechanism when the latter is inactive.

52. A stamp vending machine having a movable carrier, means for operating the carrier, stamp ejecting means operated upon 100 directly by a coin or coins deposited within the carrier when the latter is moved, means for locking the ejecting mechanism against repeating action after the carrier has moved from normal position, means for releasing the coins from the carrier after actuating the ejecting mechanism, means for distributing the coins when released from the carrier, means for supplying stamp strips to the 105 ejecting mechanism, means operated on movement of the carrier for severing the stamps from the strip when ejected, coin changing mechanism, means for rendering the changing mechanism inactive when without a predetermined number of coins, 110 means for returning the deposited coins from the changing mechanism when the latter is inactive, and means for preventing spurious coins from remaining in position in the carrier to actuate the ejecting mechanism. 115

53. A machine of the character described comprising a casing, stamp ejecting mechanism, a movable coin carrier therein and having chutes adapted to position a coin or coins for direct action upon the ejecting 125 mechanism to effect the automatic delivery of a stamp or stamps from the casing, means for releasing the coin or coins in the carrier after acting upon the ejecting mechanism, means for distributing each coin de- 130

5 posited in the carrier, means rendered operative upon the location of a coin or coins in the carrier for regulating the operation of the ejecting mechanism to determine the feed of stamps thereby, and coin changing mechanism operated by coins deposited within the carrier.

10 54. A machine of the character described comprising a casing, stamp ejecting mechanism, a movable coin carrier therein and having chutes adapted to position a coin or coins for direct action upon the ejecting mechanism to effect the automatic delivery of a stamp or stamps from the casing, means 15 for releasing the coin or coins in the carrier after acting upon the ejecting mechanism, means for distributing each coin deposited in the carrier, means rendered operative upon the location of a coin or coins 20 in the carrier for regulating the operation of the ejecting mechanism to determine the feed of stamps thereby, coin changing mechanism operated by coins deposited within the carrier, and means for delivering certain 25 coins from the carrier to the coin changing mechanism.

30 55. A machine of the character described comprising a casing, stamp ejecting mechanism, a movable coin carrier therein and having chutes adapted to position a coin or coins for direct action upon the ejecting mechanism to effect the automatic delivery of a stamp or stamps from the casing, means 35 for releasing the coin or coins in the carrier after acting upon the ejecting mechanism, means for distributing each coin deposited in the carrier, means rendered operative upon the location of a coin or coins in the carrier for regulating the operation of the 40 ejecting mechanism to determine the feed of stamps thereby, coin changing mechanism operated by coins deposited within the carrier, means for delivering certain coins from the carrier to the coin changing 45 mechanism, and means for returning a coin or coins from the changing mechanism when the latter is inactive.

50 56. A machine of the character described comprising a casing, stamp ejecting mechanism, a movable coin carrier therein and having chutes adapted to position a coin or coins for direct action upon the ejecting mechanism to effect the automatic delivery of a stamp or stamps from the casing, 55 means for releasing the coin or coins in the carrier after acting upon the ejecting mechanism, means for distributing each coin deposited in the carrier, means rendered operative upon the location of a coin or 60 coins in the carrier for regulating the operation of the ejecting mechanism to determine the feed of stamps thereby, coin changing mechanism operated by coins deposited within the carrier, means for delivering certain 65 coins from the carrier to the coin

changing mechanism, means for returning a coin or coins from the changing mechanism when the latter is inactive, and means for delivering excess coins from the changing mechanism into the casing. 70

57. A machine of the character described comprising a casing, stamp ejecting mechanism, a movable coin carrier therein and having chutes adapted to position a coin or coins for direct action upon the ejecting mechanism to effect the automatic delivery of a stamp or stamps from the casing, means for releasing the coin or coins in the carrier after acting upon the ejecting mechanism, means for distributing each coin deposited in the carrier, means rendered operative upon the location of a coin or coins in the carrier for regulating the operation of the ejecting mechanism to determine the feed of stamps thereby, coin changing mechanism operated by coins deposited within the carrier, means for delivering certain coins from the carrier to the coin changing mechanism, means for returning a coin or coins from the changing mechanism when the latter is inactive, means for delivering excess coins from the changing mechanism into the casing, and means for rendering the changing mechanism inactive when an insufficient number of coins are therein for the proper changing of the denomination of coin or coins deposited in the carrier. 85 90 95

58. A machine of the character described comprising a casing, stamp ejecting mechanism, a movable coin carrier therein and having chutes adapted to position a coin or coins for direct action upon the ejecting mechanism to effect the automatic delivery of a stamp or stamps from the casing, means for releasing the coin or coins in the carrier after acting upon the ejecting mechanism, means for distributing each coin deposited in the carrier, means rendered operative upon the location of a coin or coins in the carrier for regulating the operation of the ejecting mechanism to determine the feed of stamps thereby, coin changing mechanism operated by coins deposited within the carrier, means for delivering certain coins from the carrier to the coin changing mechanism, means for returning a coin or coins from the changing mechanism when the latter is inactive, means for delivering excess coins from the changing mechanism into the casing, means for rendering the changing mechanism inactive when an insufficient number of coins are therein for the proper changing of the denomination of coin or coins deposited in the carrier, and means for locking the carrier against reverse movement between its completed movements either forwardly or backwardly. 100 105 110 115 120 125

59. A machine of the character described comprising a casing, stamp ejecting mecha- 130

nism, a movable coin carrier therein and having chutes adapted to position a coin or coins for direct action upon the ejecting mechanism to effect the automatic delivery of a stamp or stamps from the casing, means for releasing the coin or coins in the carrier after acting upon the ejecting mechanism, means for distributing each coin deposited in the carrier, means rendered operative upon the location of a coin or coins in the carrier for regulating the operation of the ejecting mechanism to determine the feed of stamps thereby, coin changing mechanism operated by coins deposited within the carrier, means for delivering certain coins from the carrier to the coin changing mechanism, means for returning a coin or coins from the changing mechanism when the latter is inactive, means for delivering excess coins from the changing mechanism into the casing, means for rendering the changing mechanism inactive when an insufficient number of coins are therein for the proper changing of the denomination of coin or coins deposited in the carrier, means for locking the carrier against reverse movement between its completed movements either forwardly or backwardly, and means on the carrier for detecting spurious coins.

60. A machine of the character described comprising a casing, stamp ejecting mechanism, a movable coin carrier therein and having chutes adapted to position a coin or coins for direct action upon the ejecting mechanism to effect the automatic delivery of a stamp or stamps from the casing, means for releasing the coin or coins in the carrier after acting upon the ejecting mechanism, means for distributing each coin deposited in the carrier, means rendered operative upon the location of a coin or coins in the carrier for regulating the operation of the ejecting mechanism to determine the feed of stamps thereby, coin changing mechanism operated by coins deposited within the carrier, means for delivering certain coins from the carrier to the coin changing mechanism, means for returning a coin or coins from the changing mechanism when the latter is inactive, means for delivering excess coins from the changing mechanism into the casing, means for rendering the changing mechanism inactive when an insufficient number of coins are therein for the proper changing of the denomination of coin or coins deposited in the carrier, means for locking the carrier against reverse movement between its completed movements either forwardly or backwardly, means on the carrier for detecting spurious coins, and means for discharging the spurious coins from the carrier.

61. A machine of the character described comprising a casing, stamp ejecting mechanism, a movable coin carrier therein and having chutes adapted to position a coin or

coins for direct action upon the ejecting mechanism to effect the automatic delivery of a stamp or stamps from the casing, means for releasing the coin or coins in the carrier after acting upon the ejecting mechanism, 70 means for distributing each coin deposited in the carrier, means rendered operative upon the location of a coin or coins in the carrier for regulating the operation of the ejecting mechanism to determine the feed of 75 stamps thereby, coin changing mechanism operated by coins deposited within the carrier, means for delivering certain coins from the carrier to the coin changing mechanism, means for returning a coin or coins from 80 the changing mechanism when the latter is inactive, means for delivering excess coins from the changing mechanism into the casing, means for rendering the changing mechanism inactive when an insufficient number 85 of coins are therein for the proper changing of the denomination of coin or coins deposited in the carrier, means for locking the carrier against reverse movement between its completed movements either forwardly 90 or backwardly, means on the carrier for detecting spurious coins, means for discharging the spurious coins from the carrier, and means for receiving the coins from the distributing means. 95

62. A machine of the character described comprising a casing, stamp ejecting mechanism, a movable coin carrier therein and having chutes adapted to position a coin or coins for direct action upon the ejecting mechanism to effect the automatic delivery of a stamp or stamps from the casing, means for releasing the coin or coins in the carrier after acting upon the ejecting mechanism, means for distributing each coin deposited 100 in the carrier, means rendered operative upon the location of a coin or coins in the carrier for regulating the operation of the ejecting mechanism to determine the feed of stamps thereby, coin changing mechanism 105 operated by coins deposited within the carrier, means for delivering certain coins from the carrier to the coin changing mechanism, means for returning a coin or coins from the changing mechanism when inactive, 110 means for delivering excess coins from the changing mechanism into the casing, means for rendering the changing mechanism inactive when an insufficient number of coins are therein for the proper changing of the denomination of coin or coins deposited in the carrier, means for locking the carrier against reverse movement between its completed movements either forwardly or backwardly, means on the carrier for detecting 115 spurious coins, means for discharging the spurious coins from the carrier, means for receiving the coins from the distributing means, and means for returning the carrier to normal position. 120 125 130

63. A machine of the character described comprising a casing, stamp ejecting mechanism, a movable coin carrier therein and having chutes adapted to position a coin or 5 coins for direct action upon the ejecting mechanism to effect the automatic delivery of a stamp or stamps from the casing, means for releasing the coin or coins in the carrier after acting upon the ejecting mechanism, 10 means for distributing each coin deposited in the carrier, means rendered operative upon the location of a coin or coins in the carrier for regulating the operation of the ejecting mechanism to determine the feed 15 of stamps thereby, coin changing mechanism operated by coins deposited within the carrier, means for delivering certain coins from the carrier to the coin changing mechanism, means for returning a coin or coins from 20 the changing mechanism when the latter is inactive, means for delivering excess coins from the changing mechanism into the casing, means for rendering the changing mechanism inactive when an insufficient number 25 of coins are therein for the proper changing of the denomination of coin or coins deposited in the carrier, means for locking the carrier against reverse movement between its completed movements either forwardly 30 or backwardly, means on the carrier for detecting spurious coins, means for discharging the spurious coins from the carrier, means for receiving the coins from the distributing means, means for returning the 35 carrier to normal position, and means for locking the ejecting mechanism against action when the carrier is at the limits of its movements.
64. A machine of the character described 40 comprising a casing, stamp ejecting mechanism, a movable coin carrier therein and having chutes adapted to position a coin or coins for direct action upon the ejecting mechanism to effect the automatic delivery 45 of a stamp or stamps from the casing, means for releasing the coin or coins in the carrier after acting upon the ejecting mechanism, means for distributing each coin deposited in the carrier, means rendered operative 50 upon the location of a coin or coins in the carrier for regulating the operation of the ejecting mechanism to determine the feed of stamps thereby, coin changing mechanism operated by coins deposited within the carrier, means for delivering coins from the carrier to the coin changing mechanism, means for returning a coin or coins from 55 the changing mechanism when the latter is inactive, means for delivering excess coins 60 from the changing mechanism into the casing, means for rendering the changing mechanism inactive when an insufficient number of coins are therein for the proper changing of the denomination of coin or coins deposited in the carrier, means for locking the 65

carrier against reverse movement between its completed movements either forwardly or backwardly, means on the carrier for detecting spurious coins, means for discharging the spurious coins from the carrier, 70 means for receiving the coins from the distributing means, means for returning the carrier to normal position, means for locking the ejecting mechanism against action when the carrier is at the limits of its movements, and means for preventing repeating action of the ejecting mechanism during movement of the carrier.

65. In a machine of the character described, a movable coin carrier, coin changing mechanism operated directly upon by a coin or coins within the carrier for ejecting change according to the denomination of the coin or coins deposited, means for rendering the changing mechanism inactive when without a predetermined number of coins, means for locking the carrier against reversing action between initial and completed forward and backward movements thereof, means for releasing a coin or coins in the carrier after actuating the changing mechanism, means for receiving the change from said mechanism and accessible to the operator, and means for distributing and assorting the coins from the carrier.

66. In a machine of the character described, a movable coin carrier, coin changing mechanism operated directly upon by a coin or coins within the carrier for ejecting change according to the denomination of the coin or coins deposited, means for rendering the changing mechanism inactive when without a predetermined number of coins, means for locking the carrier against reversing action between initial and completed forward and backward movements thereof, means for releasing a coin or coins in the carrier after actuating the changing mechanism, means for receiving the change from said mechanism and accessible to the operator, and means for distributing and assorting the coins from the carrier, and means for delivering excess coins from the changing mechanism to the interior of the machine.

67. In a machine of the character described, a movable coin carrier, coin changing mechanism operated directly upon by a coin or coins within the carrier for ejecting change according to the denomination of the coin or coins deposited, means for rendering the changing mechanism inactive when without a predetermined number of coins, means for locking the carrier against reversing action between initial and completed forward and backward movements thereof, means for releasing a coin or coins in the carrier after actuating the changing mechanism, means for receiving the change from said mechanism and accessible to the operator, means for distributing and assorting the coins from

the carrier, means for delivering excess coins from the changing mechanism to the interior of the machine, and means for ejecting spurious coins from the carrier.

- 5 68. In a machine of the character described, a movable coin carrier, coin changing mechanism operated directly upon by a coin or coins within the carrier for ejecting change according to the denomination of the 10 coin or coins deposited, means for rendering the changing mechanism inactive when without a predetermined number of coins, means for locking the carrier against reversing action between initial and completed forward 15 and backward movements thereof, means for releasing a coin or coins in the carrier after actuating the changing mechanism, means for receiving the change from said mechanism and accessible to the operator, 20 means for distributing and assorting the coins from the carrier, means for delivering excess coins from the changing mechanism to the interior of the machine, means for ejecting spurious coins from the carrier, and 25 means for preventing the insertion of coins within the carrier when the changing mechanism is rendered inactive.
69. In a machine of the character described, a movable coin carrier, coin changing mechanism operated directly upon by a coin or coins within the carrier for ejecting change according to the denomination of the coin or coins deposited, means for rendering the changing mechanism inactive when without a predetermined number of coins, means for locking the carrier against reversing action between initial and completed forward and backward movements thereof, means for releasing a coin or coins in the carrier after actuating the changing mechanism, means for receiving the change from said mechanism and accessible to the operator, means for distributing and assorting the coins from the carrier, means for delivering excess coins from the changing mechanism to the interior of the machine, means for ejecting spurious coins from the carrier, and means for preventing the insertion of coins within the carrier when the changing mechanism is rendered inactive.
70. In a machine of the character described, a movable coin carrier, coin changing mechanism operated directly upon by a coin or coins within the carrier for ejecting change according to the denomination of the coin or coins deposited, means for rendering the changing mechanism inactive when without a predetermined number of coins, means for locking the carrier against reversing action between initial and completed forward and backward movements thereof, means for releasing a coin or coins in the carrier after actuating the changing mechanism, means for receiving the change from said mechanism and accessible to the operator, means for distributing and assorting the coins from the carrier, means for delivering excess coins from the changing mechanism to the interior of the machine, means for ejecting spurious coins from the carrier, and means for preventing the insertion of coins within the carrier when the changing mechanism is rendered inactive.
71. In a machine of the character described, a movable coin carrier, coin changing mechanism operated directly upon by a coin or coins within the carrier for ejecting change according to the denomination of the coin or coins deposited, means for rendering the changing mechanism inactive when without a predetermined number of coins, means for locking the carrier against reversing action between initial and completed forward and backward movements thereof, means for releasing a coin or coins in the carrier after actuating the changing mechanism, means for receiving the change from said mechanism and accessible to the operator, means for distributing and assorting the coins from the carrier, means for delivering excess coins from the changing mechanism to the interior of the machine, means for ejecting spurious coins from the carrier, and means for preventing the insertion of coins within the carrier when the changing mechanism is rendered inactive.
72. A stamp vending machine having a movable carrier, stamp ejecting means operated upon directly by a coin or coins deposited within the carrier when the latter is moved, means for locking the ejecting mechanism against repeating action after the carrier has moved from normal position, means for releasing the coins from the carrier after actuating the ejecting mechanism, means for distributing the coins when released from the carrier, means for supplying stamp strips to the ejecting mechanism, means operated on movement of the carrier for severing the stamps from the strip when ejected, means for operating the carrier, means for automatically returning the carrier to normal position, coin changing mechanism, means for delivering certain of the coins deposited within the carrier to the changing mechanism, means for delivering excess coins from the changing mechanism interiorly of the casing, means for rendering the changing mechanism inactive when without a predetermined number of coins,

- means for returning the coins from the changing mechanism when the latter is inactive, means for preventing spurious coins from remaining in position in the carrier to 5 actuate the ejecting mechanism, means for detecting spurious coins and ejecting the same from the carrier, and means for indicating when the stamp supply has been exhausted and also preventing coins being deposited within the carrier.
73. In a machine of the character described, a movable coin carrier, coin changing mechanism operated directly upon by a coin or coins within the carrier for ejecting 15 change according to the denomination of the coin or coins deposited, means for rendering the changing mechanism inactive when without a predetermined number of coins, means for locking the carrier against reversing action between initial and completed forward and backward movements 20

thereof, means for releasing a coin or coins in the carrier after actuating the changing mechanism, means for receiving the change from said mechanism and accessible to the 25 operator, means for distributing and assorting the coins from the carrier, means for delivering excess coins from the changing mechanism to the interior of the machine, means for ejecting spurious coins from the 30 carrier, means for preventing the insertion of coins within the carrier when the changing mechanism is rendered inactive, means for indicating when the changing mechanism is empty, means for manually moving 35 the carrier, means for returning the carrier to normal position when it has completed its forward movement, and a tray having pockets for receiving the assorted coins from the distributing means.

In testimony whereof I affix my signature.
HERBERT O. TIBBITTS.
